RECORD CONTROLLED DUPLICATE
PRINTING MACHINE

Edward J. Rabenda, Poughkeepsie, N. Y., assignor
to International Business Machines Corporation,
New York, N. Y., a corporation of New
York

Application February 26, 1949, Serial No. 78,562

14 Claims. (Cl. 101—93)

1

This invention relates to multiple line printing machines, and more particularly to the type which performs a repetition of multiple line address printing directly under control of a single record and without the necessity of utilizing storage devices, or the like.

In machines of the record controlled type, a series of item or detail cards are passed through the machine and with the incorporation of an alpha-numerical printing mechanism a plurality of items of information are listed on successive lines of the body of a bill or statement. To completely print the bill or statement it is necessary to print address data, consisting of a name, street and number, and town and state on each bill or statement. While this could be effected by passing such printed bills or statements through an address printing machine utilizing metal address plates, or stencils, there would be no assurance that the addresses would be printed on the related bills. Furthermore, this additional printing would require another machine, and expenditure of time, the latter being objectionable especially due to the present day requirements for high speed printing and accounting operations. Accordingly, it has been proposed to pass master cards through the machine and in an earlier form of address printing machine three master records carried the address data under control of which the name, street and number, city or town and state were respectively printed on successive lines. When the three master records were passed through the machine before the detail records this address data was printed in the heading of the bill or statement.

Due to the rigid requirement that the three master records had to be always in the same group as the associated detail records, this manner of operation did not possess the characteristics of simplicity and speed in operation that were desirable. It has been contemplated in a further development of such forms of record controlled printing machines to provide for the analysis or sensing of the record which carries address data representations of the name, street and number, city or town and state, in three fields in such manner that a printing mechanism which is controlled thereby prints the address data on successive lines of the bill while the record is retained in position for a repeated analysis or sensing.

One embodiment of such address printing machine is shown and described in the application of Horace S. Beattie, Ralph E. Page and James

2

F. Kerbin, Serial No. 74,424, filed February 3, 1949, to which reference may be had for further details of construction and operation. In general a single master card precedes all detail cards, and comes to rest in the sensing mechanism. Thereafter, the card is repeatedly sensed in successive cycles of machine operation. By the use of progressively operated selectors, such as successively energized relays, the fields of address data are read out in succession as they are sensed to control the printing mechanism which thereby operates to print the address data line by line on the bill in the printing mechanism. Further controls are embodied in the machine which conditions the machine for the above described mode of operation, selects the fields of data which are to be printed, the number of lines to be printed, the sequence that they are printed, and the suppression and initiation of operation of the record feeding mechanism as the address line printing operations are respectively started and finished.

In record controlled machines of the above described type it usually suffices to print one address on a bill, but there are, at times, special requirements which make it desirable that the same address printing be repeated. Such instances would be where the billing and shipping address are the same, that is to say, the same person or company would receive the goods and the corresponding bill or statement. Other requirements where duplicate addresses are desirable are also evident. The above described type of machine could secure this result by utilizing two master cards, but the same objection would prevail as for the earlier form of address printing machines, i. e. the necessity of keeping related address records and detail records together. It is to the accomplishment of this object that the present invention is concerned with and fulfills the requirement in a manner that is entirely satisfactory with respect to machine operations and efficiency.

It is, therefore, the main object of the present invention to devise a record controlled multi-line address printing arrangement in such a manner that a repetition of address printing from the same address card can be performed.

Another object of the invention is to devise a record controlled multiline address printing arrangement which automatically initiates upon completion of one address printing from one record, a repetition of address printing from the same record and to control a printing mechanism to print one address below the other.

A still further object of the invention is to provide a control for the record feeding mechanism of a record controlled address printing machine which suppresses the normal feeding of the record upon completion of printing the first address and retains the record at rest, whereby address line printing can be reinitiated under control of the same record.

A still further object of the invention is to devise a record controlled multiline address printing arrangement wherein a record is repeatedly sensed to control a printing mechanism to print an address line by line with a control which is rendered operable when an address is to be repeatedly printed which effects further repeated sensing of the same record, whereby the same record is utilized as a control to effect successive address data printing on a sheet, one below the other.

A still further object of the invention is to include in the above described address printing arrangement a line number control which is effective to select the number of lines to be printed for each address printed.

A still further object of the invention is to include in the above described address printing arrangement a line number control comprising special perforations on the record which are effective to select the number of lines to be printed for each address.

A still further object of the invention is to provide an address printing arrangement with two record sensing stations in which the address bearing record is passed from the first to the second, and to include in the first sensing station, sensing means which is set up according to the line number control perforations, so that the number of lines to be printed under control of the record when it is sensed at the second sensing station can be selected.

Another object of the invention is to devise the address printing arrangement in such manner that the repetition of address printing can be selectively controlled, in order that the machine may be conditioned to effect only one address printing from one record, or repeated address printing from another record.

A still further object of the invention is to devise the multiline printing arrangement of the record controlled machine in such selective manner that one or two addresses may be printed, as desired, under control of the same record.

Further features of the invention relate to the interlock means which prevents improper operations as operations are carried out. One interlock enables the transmission of an impulse to initiate a repetition of address printing but suppresses it when the second address has been printed, in order that address printing would not go on uninterruptedly. A still further interlock relates to the record feeding means which initiates or suppresses such operations as they should be carried out or prevented according to requirements.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a left outside elevational view of the card feeding unit and is taken on the line 1—1 of Fig. 4.

Fig. 2 is a view similar to Fig. 1 but is an out-

side elevational view of the right side of the unit and is taken on the line 2—2 of Fig. 4.

Fig. 3 is a longitudinal sectional view taken on the line 3—3 of Fig. 4.

Fig. 4 is a plan view with the upper hinged section of the unit removed and fragmentary in portions to show more clearly the parts which would be concealed.

Fig. 5 is a view in side elevation showing the gripper frame assembly and associated cam operated linkage for closing and reopening the card grippers.

Fig. 6 is a transverse sectional view taken on the line 6—6 of Fig. 5.

Fig. 7 is a transverse sectional view taken on the line 7—7 of Fig. 5.

Fig. 8 is a detail view showing a portion of a cam operated linkage for operating the gripper closing mechanism.

Figs. 9a and 9b when assembled with Fig. 9a on the top shows the construction of the numeral and alphabet printing mechanism.

Fig. 10 is a detail of an overthrow preventing mechanism.

Fig. 11 is a view in side elevation showing the intergearing for driving the shafts of the printing mechanism in synchronism.

Fig. 12 is a sectional view taken on the line 12—12 of Fig. 11.

Fig. 13 is a sectional view taken on the line 13—13 of Fig. 11.

Fig. 14 is a sectional view taken on the line 14—14 of Fig. 12.

Fig. 15 represents the preferred code for selecting alphabet and numeral type.

Figs. 16a, 16b, 16c when assembled one over the other in this order show the timing of the card feed unit, the timing of the printer unit, and the timing of cam contacts, commutators, etc. shown in the wiring diagram.

Figs. 17a, 17b, 17c, 17d and 17e when assembled side by side in the named order constitute a wiring diagram of the machine.

Fig. 18 is a diagrammatic flow diagram showing the controls for the printing of one, two or three lines under control of a single master card, or a single line under control of a detail card.

Fig. 19 illustrates a detail card and a master card, and how a form may be single-line printed, or multiple-line printed under control of the respective detail and master cards.

Fig. 20 is a flow diagram showing the controls for repeating address printing, either one, two or three lines.

Fig. 21 is a representation of a form adapted to receive a repeated address which are alike for billing and shipping instructions.

Framework of card feed unit

The card feeding unit is preferably of the construction fully described in the application of G. F. Daly, Serial No. 629,576, filed November 19, 1945, now U. S. Patent Serial No. 2,510,559.

The unit has a lower or bottom section mounted upon a base of the card controlled machine and an upper hinged section which also carries certain parts of the card feeding unit.

The framework for the bottom or lower section of the unit consists of a pair of spaced side frames 16 and 11 (Figs. 1, 2 and 4) which carry, among other parts, the bearings in which operating shafts to be subsequently described are journaled. Rigidity of the lower section of the unit is provided by cross members 12 and 13

(Fig. 3). The transverse operating shafts to be subsequently described also comprise cross members which aid in securing a rigid framework.

The framework of the upper section consists of side frames 14 and 15 (Figs. 1 and 3) and such side frames are suitably spaced by cross members which include a plate 16 (see Fig. 3). The upper framework is hinged to the lower section or portion of the unit on a pair of studs 17. Preferably, this pivotal mounting is provided by having cam plates 18 and 19 (Figs. 1 and 2) attached by rivets 20 to the side frames 15 and 14, respectively, said cam plates thus providing extensions of the side frames 14 and 15 to receive the hinge studs 17.

The card stacking magazine 23 comprises a base plate 21 and two side plates 22, each of which is pivoted on a stacker drum shaft 47 and the magazine is thus pivoted about the lower section. A catch 23a (Figs. 3) latches the card storage magazine in normal position. The magazine 23 receives cards fed by the stacker mechanism after such cards have passed through the machine to control functions in the card controlled machine.

Suitable side plates 24 (Figs. 1 and 2) together with the cross plate 16 provide a card supply magazine 25 from which magazine cards are fed singly for their presentation to analyzing or card reading stations to be subsequently described. Plate 16 is carried by the upper section and is the rear wall of the magazine. The side plates 24 are split as shown in Fig. 3 so that the upper part can be carried by the side plates 14 and 15 and the complementary portions can be carried by the lower section of the unit. This enables the upper portion of the card supply magazine to rock about studs 17 when the upper section is rocked.

All of the gear drives and rotating shafts of the card feed unit are carried by the lower portion of the unit. The power for driving the card feeding unit is derived from a continuously rotating main drive shaft 27 (Figs. 2 and 4). To shaft 27 there is secured a gear 28 meshing with a gear 29 having a 2-1 gear ratio so that for one revolution of shaft 27 the shaft 30, to which gear 29 is secured, is rotated clockwise as viewed in Fig. 2 and counterclockwise as viewed in Fig. 3 one-half revolution per machine cycle.

Shaft 30 has secured to it a gear 31 (Figs. 2 and 4) which drives a train of intermeshing gears 32, 33 and 34 which are mounted outside of the main side frame 11 and by suitable compounding drives gears 35, 36 and 37.

Inside of the side frame 11, referring to Figs. 3 and 4, a gear 38 secured to the main drive shaft 30 drives a train of gears 39 and 40.

Gear 32 is secured to a cam shaft 41 (Figs. 2 and 4) and gears 34 and 35 are secured to a cam shaft 42, both cam shafts being driven counterclockwise, as viewed in Fig. 2 one revolution per machine cycle. The gear 33 is secured to a commutator drive shaft 43 and likewise the main drive shaft 30 is utilized as a commutator drive shaft.

Gear 39 (Fig. 3) is secured to a crank shaft 44 and gear 45a to a clutch drive shaft 45, both shafts 44 and 45 being driven clockwise (Fig. 3) one revolution per machine cycle. Gear 36 (Fig. 2) is an idler gear which drives the stacker drum assembly through gear 37 and is loosely supported on a stud 46. Gear 40 (Fig. 3) is loosely mounted on a rocker shaft 47 (Fig. 75).

3). The gear 37 (Fig. 2) is secured to the stacker drum driving shaft 47.

For feeding the cards which emerge from the card supply magazine, top edge foremost and printed face down, there is provided cooperating feeding rollers 50 and 51 (see Fig. 3) mounted on the respective shafts 52 and 53 carried by the lower portion of the card feeding unit. Lower feeding roller 51 has secured thereto a gear 54 meshing with an idler gear 55 which is driven by the gear 40.

Card feed from supply magazine

A conventional card picker is provided to feed cards singly from the supply magazine and includes a card picker 58 (Fig. 3) having a swivel mounting on a slidably mounted rack 59, all of which parts are carried by the lower portion of the card feeding unit. Said rack 59 is operated by a segment arm 60 secured to a rocker shaft 61 to which latter there is secured a follower arm 62 operated by a cam 63.

To effect selective card feed operations there is provided the usual one-revolution clutch which includes a card feed control magnet 64. As in the well known construction, the armature 65 thereof rocks a clutch release arm 66 which enables a pawl 67 pivoted on the cam 63 to engage a notch 68 formed in a disk secured to the one-revolution drive shaft 45. When such clutch engagement is effected, shaft 45 will drive the cam 63 a complete revolution at which time the clutch release arm 66 will be in a position to disengage the pawl 67 from notch 68.

By electrical circuits to be subsequently described an impulse is transmitted to the clutch control magnet 64 to feed the lowermost card to the now rotating feeding rollers 50, 51. From Fig. 16a it will be noted that such rollers feed the card from the beginning of the cycle up to 200° of the machine cycle to feed the card to the first sensing station, known herein as a "presensing station." As the card emerges from the feeding rollers 50, 51, it is guided by spaced plates 69 (Fig. 3) which are carried by the lower portion of the card feeding unit and are located at the so-called presensing station P (Fig. 4).

Stacker drum

After the card has been twice analyzed and it emerges from the second analyzing station it is engaged and received by a stacker drum 70 (Fig. 3) of a conventional construction and since its construction and operation is well known it will only be generally stated that such stacker drum receives a card, turns it over and deposits it in the card stacker magazine 23 and in the same order as the cards are originally stacked in the supply magazine 25.

Card gripper feeding devices

It is preferable to positively grip the cards to feed them from station to station without resorting to the expedient of card feeding rollers, because when such cards are released by the grippers they are free to be repositioned by the aligning devices, if disaligned. As will appear later, the presence of a card in the presensing station enables the release of the grippers to seize each card and reciprocate the gripper frames to feed the card from the station in which it is located to the next station. These stations are indicated in Fig. 4 as the "Presensing Station," the second or "Control Station" which is used for control purposes in the customary card controlled

accounting machine and the third station designated as "Adding-Printing Control Station" having the functions of this legend.

In general there is provided at the right side of the card feeding unit at the lower portion thereof a reciprocable gripper frame 71R (Fig. 4) carrying card grippers 72, 73 and 74. At the other side of the machine the companionate reciprocable gripper frame 71L carries grippers 75, 76 and 77. Obviously, grippers 72 and 75 feed the card from the Presensing Station to the Control Station and simultaneously grippers 73 and 76 move a card from the latter designated station to the Adding-Printing Control Station and grippers 74 and 77 feed a card from the Adding-Printing Control Station to the stacker drum assembly 70. When three cards are at their respective stations the concomitant movement of gripper frames 71R and 71L will feed three cards during the same machine cycle.

In view of the similarity in construction of both reciprocating gripper frames 71R and 71L the detailed description of the gripper frame assembly will be confined to the construction and operation of gripper frame 71R only.

The gripper assembly is carried by an inverted U-shaped frame comprising a cross plate 80 (Figs. 6 and 7) and integral dependently hung side plates 81 and 82, plate 81 being outside of the side frame 11, and side plate 82 being at the inside of the side frame 11. The side plate 81 carries two stud shafts 83 (see Fig. 5) which provide the bearings for respective ball bearing mounted wheels 84 and 85, which wheels roll over a lower track 86 and underneath an upper guide track 87 during the reciprocation of the gripper frame. The upper edge of the side frame 11 has a rectangular longitudinal open notch 88 (Fig. 1) and on the bottom of this notch the track 86 is fastened, and extending over this notch the track 87 is attached. Rotatable on the stud shafts 83 (Fig. 7) and at each side of the wheels 84 or 85 are washers 90 enlarged with respect to the diameter of the wheels and they are so confined on the guide shafts 83 as to bear against the sides of the tracks 86 and 87 to preserve the sidewise alignment of the gripper frames during their reciprocation.

Reference numerals 72, 73 and 74 refer to the stationary plates of the grippers since they are affixed by rivets 91 to the top of the cross plate 80 and as shown in Fig. 4 extend laterally inwardly over the side marginal edges of the cards. The companion movable gripper plate 93 extends inwardly similar to the stationary gripper plate and is slidably mounted so that when free to move upwardly it will positively grip the marginal edge of the card which is between it and the companion fixed gripper plate. Movable gripper plate 93 is guided in its vertical movement by a pin 94 secured thereto, cooperating with a hole in the related fixed gripper plate. At the lower part said gripper plate has a square notch 95 cooperating with the rounded end of a toggle lever 97 which is pivoted on a guide stud or pin 96 carried by the side plate 82. In this manner the movable gripper plate is guided in its vertical movement.

To bring the movable gripper plate 93 into gripping relationship with the related fixed gripper plate, any suitable means may be provided but is preferably performed by a toggle lever system which acts quickly to enable the grippers to seize the card edge. This system comprises the lower toggle lever 97 pivoted on said stud 96

and an upper toggle lever 98 pivoted on a pin 99 carried by the movable gripper plate 93. The connecting pin 99 at the midpoint of the toggle lever connects said toggle levers and passes through a notch in the side plate 82 and is received by a hole 110 (Fig. 6) in a toggle control link 100. The toggle link 100 is mounted inside of the side plate 82 and is guided for reciprocating movement by studs 101 (Fig. 5) carried by the side plate 82 cooperating with guide slots 102 formed in the toggle control link 100. The toggle control link is normally latched by a latch lever 103 pivoted on a stud 104 carried by side plate 82, said latch being urged by a spring 105 extending from said latch lever to a stud 112 carried by toggle control link 100 to engage a notch 106 in the toggle control link 100. Thus, during the time that the three grippers are to be opened so as to be free of the marginal edges of the card, the toggle control link 100 is normally latched by the latch lever 103. At the instant when the cards are to be engaged by the respective grippers, by means to be presently described, latch lever 103 will be rocked to disengage it from the shoudered notch 106, and in so doing it tensions spring 105. This will release the toggle control link 100 and said link will be instantly moved towards the right as viewed in Fig. 5, partly by the tension of spring 105 so that by shifting each pin 99 to the right the respective toggle lever system will be straightened, elevating the lower movable gripper plate 93 and closing the gripper jaws upon the marginal edge of the card. The movement of the toggle control link 100 to the right is effected by the action of spring 105, as just stated, and three springs 107, 108 and 109, each of which is connected to the midpoint connecting pin 99 and to a respective stud 111 carried by the side plate 82. It is preferable to enable each movable gripper plate to move independently of the toggle control link 100, especially at the time that the toggle lever system is straight so that under the action of the respective springs 107, 108 and 109 the movable plate will be moved upwardly freely. This is effected by enabling toggle control link 100 to move slightly farther than connecting pin 99 of any of the individual toggle links so that the toggle lever system is under control of its respective spring 107, 108, 109. This preferred action can be effected by having each of the pins 99 operate in the hole 110 (Fig. 6) in the toggle control link 100 which is slightly larger than the diameter of the connecting pin 99.

Closing and reopening of the three grippers carried by the reciprocating gripper frame 71R is effected under control of a swinging plate 115 (Figs. 5, 6 and 7). The swinging plate 115 is carried at one end by a bell crank lever 116 pivoted on a fixed rod 114 carried by the side frame 11 and also to a stud 118 carried by said plate 115. A similar bell crank 117 is pivoted on a fixed rod 119 carried by the said frame 11 and also to a pivot stud 118a carried by the plate 115. The lower arm of each of the bell cranks 116 and 117 projects into a respective slot 120 in a gripper operating link 121. The gripper operating link 121 is slidably mounted on the side frame 11 by having its notches 122 cooperate with guide studs 123 carried by said side frame. One end of the gripper operating link carries a stud 124 fitting in a bifurcation 125 of an arm 126 secured to the rock shaft 127, which latter as shown in Fig. 4 is journaled in the side frames 10 and 11. To the rock shaft 127 is secured a follower arm 75 129 cooperating with a cam 130 and a supple-

mental follower arm 131 cooperating with a cam 132. A cam 130 is selectively connected by a clutch to the drive shaft 45 as will be presently described whereas cam 132 is permanently fixed to drive shaft 45, as shown in Fig. 4.

Assuming, as previously stated, that the grippers are to be closed and the gripper frame is to be moved to the left in a card carrying stroke from the Fig. 5 position, at this time the high portion of cam 130 will rock arm 129 and shaft 127 counterclockwise and through the pin and notch connection 124—125 the gripper operating link 121 is moved to the left as viewed in Fig. 5; rocking both bell cranks 116 and 117 clockwise to elevate plate 115, thus causing the operating portion 133 thereof to engage the lower lever 134 of latch 103, thus rocking the latch and releasing the toggle control link 100 and in the manner previously described enable the three grippers to concurrently close upon the card. After said grippers have been released to card gripping position the reciprocating gripper frame is then moved to the left in a card feeding stroke from the Fig. 5 position by means to be presently described.

After the grippers have carried the cards to the successive analyzing station the grippers, of course, should be reopened prior to their return movement, or to the right as viewed in Fig. 5, free of said cards and this function is effected by again elevating swinging plate 115 when the reciprocating frame is in such position that another operating portion 138 of swinging plate 115 is coordinated with the lower arm of a bell crank 135. The second elevation of plate 115 when the above correlation is obtained is performed by the cam 132 which, at the proper time in the operating cycle, rocks the respective follower arm 131 and shaft 127 so as to again shift the gripper operating link 121 to the left (Fig. 5). This, as previously described, will elevate plate 115 so that said operating portion 138 rocks bell crank lever 135 which is pivoted on a stud 136 carried by the side frame 11. The upper arm of the bell crank has an open notch engaging a pin 137 carried by the toggle control link 100. Rocking of the bell crank lever 135 in a counterclockwise direction will shift link 100 to the left so as to be relocked by latch lever 103 and at the same time rocking all of the toggle levers from their straight line position to the position shown in Fig. 5, to reopen the grippers.

Reference has been made to the reciprocation of the gripper carrying frame 71R and such reciprocation is effected by means of a crank disk 140 (Fig. 2) rotatable counterclockwise by the constantly rotating shaft 44 to which said crank disk is secured. Crank disk 140 carries a pin 141 which supports a rectangular driving shoe 142 which is guided in a crank arm 143 so as to ride in a slot 144 therein. Also slideable in slot 144 is a similar shoe 145 supported by a pin 146 carried by the gripper frame 71R. Arm 143 is fixed to a rock shaft 147.

Fig. 2 shows the parts just described in the position they occupy at the start of a card transporting operation, that is, at 210° of the timing diagram (Fig. 16a). Just prior to this, assuming that a card has been received in the presensing station, a clutch connection will be made as previously described to rotate cam 130 (Fig. 8) to cause the rocking of the latch lever 103 (Fig. 5) to close the grippers. With all the grippers closed, rotation of crank disk 140 through 120° will rock arm 143 sixty degrees, moving gripper

frame 71R from the left to the right with a harmonic motion to effect a quick feeding stroke and thereafter a slow return of the gripper frame while said grippers are opened. At the termination of the quick feeding stroke, at about 323°, arm 135 (Fig. 5) is rocked to cause the opening of the grippers, the slow return of the gripper frame then moving the opened grippers from the right as viewed in Fig. 2 to the left with a slow return.

While the detailed construction of the means for effecting the reciprocation of the gripper frame 71R has been described, it is to be understood that referring to Fig. 1 a similar means is provided to reciprocate the other gripper frame 71L concomitantly and comprises a crank disk 150 which operates in a similar manner a crank arm 151 which has a slideable shoe connection 152 to the reciprocating gripper frame 71L.

Obviously, if three cards have been previously fed to the three different stations movement of the gripper frames 71L and 71R to the left as viewed in Fig. 4 will enable the closed grippers carried thereby to transport the card to the next station or from the Adding-Printing Control Station to the stacker drum assembly. It is explained that when a card has been fed to the Presensing Station P, Fig. 3, it is completely free of the feeding rollers 50 and 51 so that seizure by the grippers 72 and 75 will convey the card to the Control Station. Furthermore, as shown in the timing diagram of Fig. 16a, during the time that the grippers are returned while open, the feeding rollers 50 and 51 are feeding a card to the Presensing Station since it is then empty (see Fig. 16a, for timing of Feed Rolls 50—51).

During the operation of the machine, the gripper frames constantly reciprocate once for each machine cycle, since drive shaft 44 is constantly rotating. Since cam 132 (Fig. 4) is also secured to the constantly rotating shaft 45, bell crank 135 (Fig. 5) is rocked once for each machine cycle whether or not the grippers have previously been closed. The closure of the grippers, however, is an independent selective operation. By an electrical impulse circuit to be subsequently described, a clutch control magnet 153 is energized (see Fig. 4). This magnet is similar to clutch control magnet 64 and causes the clutch engagement of a similar type of clutch so as to effect a driving engagement between cam 130 and the drive shaft 45. This clutch connection will then enable elevation of swinging arm 115 to cause the closure of the grippers in the manner previously described.

Card analyzing or reading mechanism

The analyzing mechanism has been devised for analysis while at rest of a card of the type shown in the patent to C. D. Lake, No. 1,772,492, granted August 12, 1930. In general, the card 154 (Fig. 4) has perforations (not shown) which are arranged in vertical columns and in horizontal rows, through which perforations electrical circuits are made to control functions of the machine. The general outline of three such cards 154 is shown in Fig. 4.

A frame 160 (Fig. 3) carries for each analyzing station a plurality of metal current carrying members 161, one for each card column and each carrying a plurality of angularly positioned metal analyzing brushes 162 which encounter the perforations and pass through to complete the electrical circuit. Plates 161 are insulated from each other and are attached to the frame 160 by

insulating rods 163. By an electrical connection to each plate 161 current is supplied to the electrical analyzing brushes 162. For each card column a set of brushes 162 makes selective contact through the perforations in the column to extensions 163 of emitter contact points 164. A brush readout 165 driven by the shaft 43 or 30 counterclockwise makes successive contact with the contact points 164 to transmit impulses in the order 9, 8, 7, 6, 5, 4, 3, 2, 1, 0, X, R at differential times, dependent upon the location of the perforation.

The above described arrangement of analyzing brushes and readout commutator is duplicated for each card column and the assembled arrangement is duplicated for the Adding-Printing Control Station and the Control Station, the commutator readouts being driven by the shafts 30 and 43.

The analyzing brush carrying frame 160 is carried by the upper portion of the card feeding unit and is mounted between the side plates 14 and 15 in the following manner: At the ends of the frame 160 (Figs. 2, 3) studs 166 and 167 carried thereby are the pivotal connections of links 168 and 169, each of which is also connected by a stud 170 to a related bell crank 171 which is pivoted upon a rod 172 carried by the side frames 14 and 15. A link 173 (Fig. 2) is connected by studs 156 and 157 to the bell cranks 171 at the same side of the frame 160. Link 173 is the controlling member of a parallelogram linkage by means of which the analyzing frame 160 is dependently hung so that by movement of said link 173 the analyzing frame 160 may be elevated and lowered, insuring the passage of the analyzing brushes through the correlated perforations. While the specific description has been confined to the supporting structure for one side of the analyzing support frame, shown in Figs. 2 and 3, the same type of support is provided for the other side of said frame as is shown in Fig. 1, wherein controlling link 174 designates the controlling member for the parallelogram linkage. Shifting of the links 173, 174 in one direction or the other to elevate or depress the analyzing frame is effected by follower arms 175 and 176 (Figs. 1 and 2) which are operated by respective complementary cams 177 and 178 secured to the drive shaft 41. The connection between the follower arm 176 or 175 and the respective controlling member link 173 or 174 consists of an open notch 179 on the follower arm receiving a stud 180 carried by the related link 173 or 174.

In Fig. 3 the analyzing frame is shown in depressed position with the readout commutators in the rotated position they occupy shortly after the emitter impulses are initiated.

During the time that the emitter impulses are being transmitted the card gripper frames with opened grippers are returned with a slow return stroke, thus enabling the cards to be held in analyzing position. After the analysis of all index point positions by the sensing or readout commutators which occurs by about 183° and prior to the movement of the gripper frames to feed the cards to the next station the complementary cams 177 and 178 are effective to rock the controlling link 174 to the left (Fig. 1) and the link 173 to the right (Fig. 2), rocking the bell cranks 171 to elevate links 168 and 169 to raise the analyzing frame 160, positioning all the analyzing brushes out of contact with the cards in the analyzing stations.

Near the end of the machine cycle, or at about 75° curately align the cards which are analyzed.

330° (see Fig. 16a), cams 171 and 178 are then effective to reverse the movements of links 173 and 174 which results in the lowering of the analyzing frame and maintenance of the frame in lowered position during the time of emission of the impulses by the readout commutators.

While the movement of the frame downwardly exerts pressure on the flexible brushes 162 to cause them to project through the perforations and make firm electrical contact, it is desirable to effect a slight lateral movement of the frame 160 so as to wipe the brushes over the card and if in contact with a commutator contact point 164 to wipe the brush thereover to make an efficient electrical contact. This is preferably effected by displacement of the frame 160 slightly to the right (Fig. 3) when the brushes are in contact with the card to be analyzed. To effectuate this there is secured to drive shaft 42 a cam 182 (Fig. 1) which operates a bell crank follower arm 183 loosely pivoted on the shaft 43. The upper arm of said bell crank has an open notch 184 which receives a stud 185 carried by the frame 160 and which projects through a clearance notch 186 in the side frame 15.

Assuming that the analyzing frame 160 is in the elevated position, cam 182 will be effective at about 251° of the machine cycle (see Fig. 16a) to shift frame 160 slightly to the left (Fig. 3), thus restoring frame 160 from its previously displaced position to the right. Near the end of the machine cycle or at about 330° the sensing frame is in lowered position and at about the time the analyzing brushes come in contact with the card cam 182 will rock the follower arm 183 to displace the frame 160 to the right, thus wiping the analyzing brushes, either over the surface of the card or over the tops 163 of the contact points 164 where perforations are encountered.

40 *Card stops and aligners for horizontal edges of cards*

The card feeding unit now being described and employed in connection with the present invention is provided with card stops and aligners which align the card along the horizontal edges to accurately correlate the horizontal rows of index points of the card with the related rows of analyzing brushes. The horizontal edges of the cards define the longer edges thereof because as the card is ordinarily held up for view by an operator the longer edges are horizontal and the shorter (left and right marginal edges) are the vertical edges. All of the horizontal edge aligners and card stops are carried by the lower portion of the card feed unit and are visible as shown in Fig. 4 when the upper section has been elevated or removed.

Since the card stops and aligners form no part of the present invention and are fully shown and described in the aforementioned patent application of G. F. Daly, Serial No. 629,576, filed November 19, 1945, they are not shown and described in detail herein.

In general, referring to Fig. 4 the feed rollers 50 and 51 project the leading edge of the card at the Presensing Station against two aligners, 190 and 191. The card at the Control Station is aligned between card stops 192, 193 and aligners 194, 195, and the card at the Adding-Printing Control Station is aligned between card stops 196, 197 and aligners 198, 199. The card stops and aligners function in the manner fully described in the Daly application, Serial No. 629,576, to accurately align the cards which are analyzed.

Vertical card edge aligners

Also as more fully shown and described in the application to G. F. Daly, Serial No. 629,576, filed November 19, 1945, now U. S. Patent No. 2,510,559, provision is also made in the card feeding unit to align the cards at the vertical edges. Since such aligners, their construction and the means for operating them are fully described in the already identified Daly application they need not be described in detail herein. In general, they comprise vertical aligners 252 and 253, a pair being disposed at the Control Station and the Adding-Printing Control Station and are preferably disposed only at these stations since any possible irregularity or deviation of the card from its proper line or direction of feed as it is fed to the Presensing Station is not of any consequence. If it occurs, it is corrected at each of the analyzing stations to accurately correlate the vertical columns of index point positions with the correlating columns of the analyzing brushes 162.

In Fig. 4 there is shown in dotted lines the relative position of each pair of vertical card edge aligners 252 and 253 and are shown in this manner because they are actually carried by the upper section of the card feed unit, as will be seen in Fig. 1.

By the operating means shown and described in the aforementioned application of G. F. Daly, Serial No. 629,576, the aligners are operated to shift a card endwise, either to the left or right as the lower ends of both aligners move downwardly and inwardly during the aligning operation.

An adjustable means is also provided to initially adjust the vertical card aligners so that as a result of the analyzing operation the card will be in the proper analyzing position with respect to its vertical columns.

Printing mechanism

In Fig. 9a reference numeral 338 designates the printing impression drive shaft which is driven with a uniform speed of rotation for each cycle of the operation of the machine. The main drive shaft 27 which rotates one revolution for each machine cycle has secured thereto a large gear 340 (Figs. 11 and 12) which drives a gear 341 secured to the printing impression drive shaft 338 to rotate the latter at a uniform speed of rotation one and a half revolutions for each revolution of drive shaft 27. Reference numeral 339 designates the type selecting drive shaft which rotates two and one-twelfth revolutions for each operating cycle. At times shaft 339 is driven with a uniform speed of rotation substantially synchronous with the drive shaft 338, but at other times the speed of rotation given to shaft 339 is decreased or increased with respect to the drive shaft 338 for a purpose to be more clearly understood later on. The variable drive for driving shaft 339 at the desired speed will now be described in detail.

Means to drive shaft 339 at variable speeds

To the side of the gears 340 (Figs. 12 and 14) and at the periphery thereof there are secured segmental bearing plates 342, 343. The plate 343 is provided with bearing slots 344 and plate 342 with bearing slots 345. Slidably mounted in such bearing slots is a cam follower plate 346. Hence, plates 342, 343 provide the bearing or support for the slidably mounted cam follower

plate 346. Obviously, since the gear 340 carries in this manner the cam follower plate 346, the latter rotates with the gear 340 about the shaft 27 in the same counterclockwise direction (Fig. 11).

Cam follower plate 346 carries a cam follower roller 347, fitting in a cam race 348 of a cam plate 349 which is fixed by studs 350 to a stationary frame plate 351. The cam follower plate 346 has an extension 352 (see Figs. 11 and 14) which carries a stud 353 (Fig. 12) and carried by the stud 353 is a square block 354 fitting between plates 355 secured to one side of a gear 356. So far it is obvious that drive shaft 27 drives the gear 340 and through the connecting cam follower plate 346 the gear 356 is driven. The cam race 348 is so designed that the cam follower plate 346 may be moved away from or towards the center of the shaft 27 and to do this without interference the plate 346 has a longitudinal slot 357 (Fig. 14) encircling the shaft 27. Also in view of the movement given to gear 356 at times resulting from the movement given to cam follower plate 346 by the cam race 348 and which movement is relative to the gear 340, the gear 340 has an elongated slot 358 (Fig. 14) through which the stud 353 passes.

The gear 356 (Figs. 11 and 13), through the gear 359, drives the type selecting drive shaft 339 and thus the latter through the variable gear drive just described is driven at a variable speed through the operating cycle of the printing mechanism. For the proper operation of the machine disclosed herein main drive shaft 27 is driven counterclockwise as viewed in Fig. 11.

A group of type consisting of three alphabet type and one numeral type is allocated for each impulse 1-9, as shown in the code of Fig. 15. Shaft 339 is driven at a uniform speed of rotation between 120° and 270° and for each 15° four printing type (4T) pass the printing line (see Fig. 16b). At about 270° the speed of rotation of the shaft 339 starts to decrease so as to present four printing type past the printing line for 27°. Between 120° and 270° of the cycle of operation the roller 347 will cooperate with a substantially concentric portion of the cam race 348, and since there will be no movement of cam follower plate 346 during this period gear 356 will be driven counterclockwise at the same speed of rotation as the gear 340. When the cam follower roller 347 enters an eccentric cam portion between 270-300° the speed of rotation of the shaft 339 is reduced so that four printing type are presented for 27°. Between 300-345° the eccentric part of cam race 348 so reduces the speed of shaft 339 that for each 15° only one printing tooth (1T) will pass by the printing point. At 300° the alphabet type which would be selected by the 0 impulse will be adjacent the printing line. At 315° of the cycle of operation the alphabet type of the selected group selected by the X impulse will be in position for printing at 330° the alphabet type selected by the R impulse will be in a position to print and at 345° the numeral type of the selected group will be in position to effect an imprint therefrom. Therefore, the slowing down of the speed of the rotation of shaft 339 is provided to selectively effect printing from the selected alphabet or numeral type of the selected group.

During the time that the cam follower roller 347 enters the very eccentric cam portion of cam race 348 between 300°-345°, the cam follower plate 346 under control of the cam race

15

348 moves outwardly (Fig. 11) with respect to the center of the shaft 27, thus, rotating the gear 356 in a clockwise direction opposite to the counterclockwise direction of rotation of the gear 340. This will result in diminishing the speed of rotation of the gear 356 and shaft 339 during the transmission of the 0, X and R zone impulses as just described.

After this reduction in speed of gear 356 the follower roller 347 then enters the cam portion after 345° and the latter is so designed as to move plate 346 inwardly (Fig. 11) towards the center of shaft 27 to cause gear 356 to rotate counterclockwise at a speed increased with respect to the gear 340. This increase in speed is initiated at 345° of the operating cycle and continues on over to the next operating cycle to 120° thereof. This increase in speed during such portions of successive machine cycles ensues to make up for the previous relative displacement of gear 356 so that at 120° of the cycle the gears 340 and 356 and parts driven thereby are always at the same relative position.

Alphabet printing mechanism

The machine is preferably provided with alphabet type and the impulses transmitted by the commutators select such type so as to print, aside from numerals, letters making up words or abbreviations, for thus printing each line derived from the card analyzed.

The printing mechanism shown herein is shown and described in complete detail in the patent to R. E. Page and H. S. Beattie, No. 2,438,071, dated March 16, 1948.

The alphabet type are selected by impulses according to the code shown in Fig. 15. The particular 0, X and R impulse determines which of the several type of a group selected by an impulse 1-9 will be printed. For example, if the impulse is "2" and no pilot impulse is utilized, i. e. either the 0, X or R impulse, the digit 2 will be printed. If an impulse is also at 0 such impulse will select the type S; if the X impulse type K will be selected and if the R impulse type B will be selected.

Each impulse 1-9 selects a group of three non-numeral type and also a numeral type. As will be later described, if a numeral type is to be selected for printing the printing impression will be taken at the "N" point in the machine cycle, which point is after the R zone impulse. The alphabet type selection is provided for by taking printing impressions before the time a numeral type would have been printed and this is effected under control of the 0, X and R impulses.

If the impulse is 9 alone a printing wheel 360 (Fig. 9a) will be rotated counterclockwise until the 9 type is at the printing line and then the printing wheel 360 will be rocked by the N pulse to effect the printing impression. It will be noted that if the zone impulse is R then under control of this impulse the printing wheel will be rocked earlier than for printing the digit 9 to take an imprint from the I type. The X zone impulse will rock the printing wheel 360 to take an imprint still earlier to print R and the impulse 0 even still earlier to print Z.

The same principle of operation is provided for selecting the type of the other groups of alphabet type and the operation of the printing mechanism for effecting type selection and printing impressions will now be described in detail.

16

The impulses are transmitted under control of each readout commutator in the order 9, 8, 7 . . . 1, 0, X and R.

When the 9-1 impulses are transmitted a circuit is closed to a printing control magnet 61 (Fig. 9b) and for each column there is a printing control magnet. In the present machine by mechanisms to be subsequently described in detail, this initiation is effected by the actuation 10 of an operating link 363 (Fig. 9a) at a differential time. For selection of type groups determined by the impulses 9-1, such operating link 363 is shifted to the left at differential times 15 between 135-270° of the operating cycle as is shown in the timing diagram (Fig. 16b). It will also be recalled that during this time shaft 339 is being rotated at a uniform speed of rotation. The shifting of the operating link 363 at differential times is provided herein to transmit a differentially timed mechanical impulse to trip the type selecting clutch shown in Fig. 9a, and now to be described in detail.

For each printing order there is pivoted on 20 a rod 366 a triple arm member consisting of arms 364, 365 and a clutch release arm 367.

Shaft 339 has secured thereto a tube 368 which is fluted transversely along its periphery to provide clutch notches 369. Tube 368 constitutes the driving clutch member. Encircling 30 the clutch tube 368 is a plurality of gears 370, there being one gear for each order of the printing mechanism. For mounting the gears 370 on the clutch tube 368, each gear has integral therewith a flange 372. To provide for the lateral spacing between the gears 370, the gears are guided by guide slots 371 formed in guide blocks 373, 374 and 375. By such spacing members the gears 370 are separated to allow independent rotation and also to locate a clutch pawl 376 which is pivoted on the related gear to cooperate with the clutch release arm 367. The clutch release arm 367 normally holds the clutch pawl 376 in such position that its tooth 377 is out of engagement with any of the clutch notches 369 40 of the clutch tube 368. When the clutch release arm 367 is rocked as a result of the actuation of the operating link 363 at a differential time the clutch is engaged because a spring 378 attached to clutch pawl 376 will rock the latter in order that the clutch tooth 377 will engage a notch 369 determined by the differential time the operating link 363 is actuated. The above described clutch is the printing type 45 selecting clutch and causes the differential rotation of the printing wheel 360, since the gear 370 and the printing teeth of the type carrying wheel 360 are intergeared.

Figs. 9a and 9b show the arrangement of the printing devices for a single order and the machine is preferably provided with a number of such devices for printing a plurality of characters.

If the operating link 363 was shifted at about 138° as a result of the 9 impulse, the clutch release arm 367 would be rocked at this time and pawl 376 would be released and rocked by spring 378 so that clutch tooth 377 engages a clutch notch 369 and printing wheel 360 will thereafter continue to rotate to such position as to 50 successively present the characters Z, R, 1 and 9 of the group selected by the 9 impulse (see Fig. 15) to the printing line between 333°-345°. The differential time at which the operating link 363 is actuated determines the extent of counterclockwise rotation of the printing wheel 360 neces-

sary to select a group of type for printing between 330°-345°. After the predetermined extent of rotation of the printing wheel 360 has been effected and the printing impression has been effected, with the type selecting clutch still engaged, the printing wheel 360 will continue to rotate until the free end of the clutch pawl 376 strikes the clutch release arm 367 which, in the meantime, has been brought to its normal position, by means of a compression spring 379 (Fig. 9a). When such disengagement is effected the printing wheel 360 is at the normal position shown in Fig. 9a.

Each printing wheel 360 is carried by an arm 381 loosely pivoted upon a rod 382 and provided with a rearwardly extending follower extension 384 which is operated by a cam projection 383 of a cam disk 385 which constitutes a driven member of a printing clutch.

Shaft 338 rotates a clutch tube 386 fixed thereto and likewise encircling the clutch tube 386 is the driven clutch disk 385 upon which is pivotally mounted a clutch pawl 387. Clutch disk 385 and parts carried thereby are guided similarly to gear 370. Associated with the clutch pawl 387 is a clutch release arm 388. When the clutch engagement is effected between the clutch pawl 387 and one of the clutch notches of the clutch tube 386, the disk 385 will be rotated in a clockwise direction, whereby the cam projection 383 will cooperate with the follower extension 384 to rock arm 381 about the rod 382 against the action of a return spring 389. The engagement of the clutch now being described is effected at differential times when the printing control magnet 361 for each order is energized for the second time under control of one of the 0, X and R impulses.

At the present time it should be understood that while the 0, X and R impulses are being transmitted the clutch release arm 388 will be rocked to clutch release position. As a result of this clutch engagement, the cam extension 383 approaches the follower extension 384 at the time shaft 339 is rotating at a diminished speed between 330°-345° to present the type of selected group successively to the printing line. Thus, the particular type which is to be selected from the selected group for printing will depend upon the differential time that the printing control magnet 361 receives a second impulse and, therefore, the time at which the printing clutch is engaged. If the 0 impulse is transmitted the printing clutch is engaged at the earliest time so as to select the first alphabet type of the selected group. If the impulse is X the printing clutch is engaged at a later time when the next alphabet type of the selected group is at the printing position and obviously when the impulse is R the printing clutch will be engaged at a still later time when the third successive alphabet type of the selected group is at the printing position. By the engagement of the printing clutch at a differential time the desired alphabet type and the numeral type of the selected group may be selected.

When the printing clutch engagement has been effected each cam 385 will cooperate with the related follower extension 384 to rock the associated printing arm 381 to force the printing wheel 360 against the usual inking ribbon and platen 390 around which is positioned the paper strip to be imprinted. As each arm 381 is rocked against the action of the spring 389, the print-

ing wheel 360 is being rotated counterclockwise but since the printing wheel is now rolling over the gear 370, this rolling action will cause an equal and simultaneous rotation in a clockwise direction. Both of these opposite rotations will, in effect, cause the printing wheel to be immobile with respect to its rotation when it moves to the right to strike the platen 390, the type striking the platen squarely and firmly to cause a legible impression.

After the printing operation, when cam extension 383 of the cam disk 385 passes by the follower extension 384, spring 389 will now be effective to return the type wheel carrying arm 381 to normal position and the extension 384 now bears against the circular peripheral edge of the cam disk 385.

After the printing operation, since the type selecting clutch is still engaged, the printing wheel 360 continues to rotate as previously stated until the clutch pawl 376 strikes the clutch release arm 367 which, in the meantime, has been positioned to normal, thereby disengaging the type selecting clutch when the printing wheels are at normal position.

The printing clutch continues its engagement for a complete rotation of the cam 385 and clutch disengagement is effected by the engagement of the clutch pawl 387 with the clutch release arm 388.

It has been found in practice that when the disengagement of the pawl 376 for the type selecting clutch is effected by striking the clutch release arm 367, there is a tendency of the clutch pawl 376 to rock counterclockwise about its pivotal point, unduly stretching the spring 379. To prevent this action a cushioning arrangement is provided to hold the pawl 376 and is shown partly in the lower right-hand corner of Fig. 9a and more completely in Fig. 10. In a preferred arrangement this constitutes for each type selecting clutch a double arm 392. One arm cooperates with a cam portion 393 of the clutch pawl 376 and the other arm bears against a spring-pressed plunger 394 inserted in an aperture 395 partly filled with oil. As the clutch pawl 376 comes around to its normal position, it will strike the clutch release arm 367, forcing its clutch tooth 377 out of the clutch notch 369 it previously engaged and the cam portion 393 of the clutch pawl 376 will strike one arm of the double arm 392, forcing the opposite end downwardly to press the plunger 394. This will force the oil out of the bottom of the recess 395 and around the plunger 394, thus providing a cushioning action on the arm 392 to restrain the clutch pawl 376 so that it cannot move too far outward.

As the free end of the clutch pawl 376 strikes the clutch arm 367 there is a tendency to cause the gear 370 to rebound counterclockwise. This action is prevented by the cooperation of a spring-pressed detent 396 with a shoulder 397 of a plate 398 secured to each gear 370. When the normal position of the clutch is obtained, the detent 396 will engage the shoulder 397 to prevent such rebound and retain the clutch parts in their normal position.

A somewhat similar rebound preventing mechanism is also provided for the printing clutch which consists of a spring-pressed detent 391 cooperating with the shoulder 399 of the cam disk 385.

Translating and impulse converting arrangement

The purpose of the above entitled arrangement herein is to translate and convert differentially timed electrical impulses to mechanical impulses and delay the transmission of each mechanical impulse to a later point in the cycle for the purpose of selecting a group of type corresponding to the differentially timed electrical impulse transmitted.

Herein the converted and delayed mechanical impulse is used for the purpose of type group selection. The arrangement for one denominational order is shown in Figs. 9a and 9b.

Cams 400A, 400B, 400C and 400D are driven by driving means to be subsequently described one revolution for each cycle of operation of the machine. It will be noted that these cams differ in their cam contours and the particular cam portion which is effective in each point of the operating cycle is shown in the timing diagram of Fig. 16b. Each of the cams is provided with cam heights which are identified by three dotted circles associated with the cam 400A (Fig. 9b), which circles are of three different diameters and represent the heights of the cam contours as "low," "medium" and "high." The corresponding designation is shown in the timing diagram of Fig. 16b for such cams to identify the particular cam portion effective in each point of the operating cycle. The cams 400A, 400B, 400C and 400D may for convenience in construction be extended longitudinally as shown in Figs. 12 and 13 to provide fluted cam rods having the configuration and outline shown in Fig. 9b to cooperate with a plurality of orders.

Each cam 400 cooperates with a related releasing and blocking member 410. The reason that the member 410 is called releasing member is that when elevated a predetermined distance by the "medium" or "high" cam portion of the related cam 400 it will release the operating link 363 for movement but when in its normal lower position (due to the "low" cam portion) it will block the link 363 against movement. Each member 410 is slidably mounted in a slot 401 of a guide block 402 and is further guided by a rod 404 which receives a guide slot 403 of the related member 410. Also pivoted on a rod 405 carried by the block 402 is a latch pawl 406. Interposed between the pawl 406 and the associated member 410 is a compression spring 407, the spring 407 functioning to urge the member 410 downwardly so as to always press against and contact with the cam contour of the related cam 400. Each member 410 is provided with a shoulder 408 cooperating with a lug 409 formed as an integral part of the link 363.

The link 363, referring to Fig. 9a, is slidably mounted in guide slots formed in a support plate 411 to support the link 363 at one end and guide its movement, and referring to Fig. 9b the other end of the link 363 is dependently hung by arm 413, which arm has a cam follower extension 418. A compression spring 414 fitting in a spring support and guide block for arm 413 urges the link 363 to the left and when such spring is effective for action under control of a cam 425 it serves as the source of mechanical impulse transmitted to link 363 at a differential time to rock the clutch release arm 367 to initiate type group selection.

Recalling now that each cam 400 has cam contours of three different heights, it should be observed that when member 410 is at a position determined by the low portion of the cam 400, the

shoulder 408 abuts lug 409 to block the link 363 from movement to the left, urged by expansion of the spring 414. In attempting to do so lug 409 will bear against the shoulder 408 and urge the member 410 clockwise, which movement is restrained by the cooperation of an upstanding hooked portion 412 of member 410 against the latching end of the pawl 406. Assuming now that a cam has been rotated so that the "medium" cam portion of the cam contour has raised the member 410, such difference in cam height with respect to the "low" cam height will elevate shoulder 408 slightly further above the related lug 409 and by the continued cooperation of the hooked extension 412 of the member 410 with the extremity of the pawl 406, clockwise movement of the pawl 410 will be still restrained.

Assuming now that the "high" cam portion has positioned the member 410 to its maximum height, the shoulder 408 will be still further above the lug 409 and the member 410 is now in such position that the compression spring 407 will be effective to rock the member 410 clockwise so that a hooked extension 412 will catch over the latch end of pawl 406, provided that at this time the pawl 406 is rocked counterclockwise due to the concurrent transmission of an impulse at the time the member 410 is in its highest position. If the pawl 406 is not rocked slightly counterclockwise, no latching of the member 410 will take place. Summarizing, whenever the "high" portion of a cam has elevated a member 410 to the highest position, such member will be latched if the related pawl 406 is concurrently rocked to latching position. If there is no rocking of the pawl 406 at this time, member 410 will not be latched, and will be subsequently free to move up and down in accordance with the successive cam contour as the related cam 400 rotates.

The above description has been confined to the operation of the parts under control of the cam 400A but it should be noted that identical operations are effected under control of the remaining cams 400B, 400C and 400D. For this reason, the description of operation need not be repeated for duplicate parts.

For the purpose of rocking the pawls 406 to latch those members 410 which are at their highest position at the time an impulse is transmitted, it will be seen that referring to Fig. 9b each magnet 361 when energized attracts an armature 415 and rocks the same so as to shift a related connected link 416 to the left. Depending from the link 416 are four integral extensions 417, each of which cooperates with the related pawl 406. The result of this construction is that the impulse directed to the magnet 361 will shift the link 416 and rock the four pawls 406 concurrently but only that pawl 406 is effective for latching the related member 410 if the associated member 410 has been elevated to its highest position. Therefore, one or more of the pawls 406 may be rocked idly at the same time without latching the related members 410.

To prevent the armature 415 from sticking to the core of the magnet 361 due to residual magnetism, it is desirable to provide means to positively restore the link 416 and armature 415 to normal by mechanical means timed with the rotation of the cams 400. To this end there is provided at magnet knockoff cam 420 (Fig. 9a) notched as shown. A follower arm 421 of a clutch release arm 424 cooperating with the cam 420 has a mechanical connection 422 with the link 416. At the time the magnet 361 is energized

it will be observed that follower arm 421 cooperates with a notch 420a of the cam 420. Thereafter, such arm cooperates with the following cam portion 420b to rock arm 421, link 416 and armature 415, restoring the armature 415 to normal if it should remain attracted to the core under the above circumstances.

Referring now to Fig. 16b, it is obvious that at the time the impulses 9-1 are transmitted under control of a readout commutator, one or more cams 400 will have their "high" portions in cooperation with the latching members 410. At the time the 9 impulse is transmitted the high portions of cams 400A and 400C will be effective. At the time the 8 impulse is transmitted only cam 400A will have a high portion effective at this time. For all of the impulses 9-1, this condition may be represented by the following table:

Impulses	Members 410 Latched
9.....	410A, 410C
8.....	410A
7.....	410B, 410C, 410D
6.....	410B, 410C
5.....	410B, 410D
4.....	410D, 410C
3.....	410B
2.....	410C
1.....	410D

It is obvious from the above table that members 410 are latched singly or in predetermined combinations, so that at the termination of the transmission of the impulses 9-1, some of the members 410 will be latched and others will not be latched and therefore free to be positioned according to the contour of their cams during their subsequent rotation. It is explained that once a member 410 is latched it is not free to thereafter move upwardly and downwardly in accordance with the subsequent cam contour of the related cam, but remaining unlatched members can do so.

Cam 425 through driving means to be subsequently explained, is driven synchronously with the cams 400 and 420 and cooperates with the follower extension 418 of arm 413.

After latching of members 410 in predetermined combinations the contour of the cams 400A, 400B, 400C and 400D which are thereafter effective will determine the time in the operating cycle that the operating link 363 will be moved to the left in a manner now to be described in detail:

After one or more members 410 are latched in combination according to the impulses transmitted as indicated in the preceding table, the further rotations of the cams 400 will raise and lower the remaining unlatched members 410 according to the cam contours of the respective cams, but during said further rotation of the cams the link 363 will be restrained against movement by one or more of such unlatched members until a point is reached in the operating cycle when the cams related to the unlatched members concurrently present cam operations of "medium" height to the unlatched members. It will be recalled that since the unlatched members 410 are so positioned that they do not restrain the movement of the link 363 under the influence of the spring 414 and further the elevation of any unlatched member by a cam portion of "medium" height will also unlock

the link 363, it is obvious that when both of these conditions exist for four of the latches 410, the link 363 is then free to move under the influence of the spring 414 and cam 425. This will be made clear by reference to a particular example.

If, for example, the 9 impulse is selected, members 410A and 410C are latched due to the "high" cam portion of their respective cams 400A and 400C and such latching of members 410A and 410C occurs about 7½° of the operating cycle when the 9 impulse is transmitted (see Fig. 16b). At this time the members 410A and 410C are latched in the highest position so that they unlock the operating link 363 at such positions. However, cams 400B and 400D in their subsequent rotation continue to raise and lower the related unlatched members 410B and 410D and one or the other of such unlatched members 410B, 410D will restrain the operating link 363 from movement until about 138° of the operating cycle, at which time both cams 410B and 410D, through their "medium" high cam portions, shift related latching members 410B and 410D to unlock the link 363. At this time cam follower extension 418 of the arm 413 will cooperate with the notch 425b designated "9" in both Fig. 9b and the timing diagram of Fig. 16b. Operating link 363 is now unlocked at four points and the movement of the link to the left is effected at about 138° by spring 414. The link will now operate the clutch release arm 367 and therefore engage the type selecting clutch to initiate the rotation of the printing wheel 360 to select the group of type, 9, Z, R and I.

The type selecting clutch will be engaged at about 150° of the operating cycle and from the timing diagram (Fig. 16b) the type carrying wheel 360 will rotate 4, 4, 4, 4, 4, 4, 4, 4, or 40 thirty-six teeth, and at about 300° of the operating cycle the Z type will now be in position to print. At 300° of the operating cycle, the speed of rotation of the type wheel is decreased to successively present the type of selected group in the order Z, R, I, and such type are selected for printing in accordance whether the pilot impulse is 0, X or R.

Reverting now to Fig. 9b, when the operating link 363 is moved to the left to effect the engagement of the type selecting clutch the cam follower extension 418 is in the bottom of the notch 425b of the cam disk 425 and further rotation of the cam 425 in a clockwise direction will, through the following inclined cam portion 425c, 55 cooperate with the cam follower extension 418 to positively restore the operating link 363 to the right without, however, causing the unlatching of any latched member 410. At about 330° an extra high cam portion 425d will shift link 363 to the right beyond the Fig. 9b position, and in so doing for those members 410 which have been latched lug 409 will engage the shoulder 423 of the respective member 410 to rock the same counterclockwise to unlatching position, 60 spring 407 being compressed during this operation to rock the pawl 406 to normal position shown in Fig. 9b. With respect to any unlatched member 410, movement of the operating link 363 to the right at this time may also effect 65 movement of such members 410 but the operation of such is ineffective.

It is desirable to provide means to insure that the clutch release arms 367 are at their normal position and will remain so when engaged by 75 the extremity of each of the clutch pawls 376

to unlatch the latter from the ratchet teeth 369. Such means now to be described is independent of the springs 379. Referring to Fig. 9b there is pivoted on a shaft 428 a plate which has fixed thereto a comb plate consisting of spring formed fingers 429 which bear against the lower extensions 365 of the clutch release arms 367. Attached to shaft 428 is a follower arm 430 carrying a roller 431, cooperating with a cam 432 secured to a drive shaft 443. From Fig. 16b it will be seen that a cam rise 432a operative at about 306° of the operating cycle is effective to cooperate with the follower roller 431 to rock the shaft 428 counterclockwise, pressing the spring fingers 429 against the related extensions 365 of the clutch release arms 367, positively retracting them to the normal position shown in Fig. 9a. Thus, it is insured that clutch release arms 367 will be in such position that they will be in the path of the free ends of the clutch pawls 376 to move them to unclutching positions.

A low portion 432b of such cam 432 is effective to enable the follower arm 430 to be rocked by a spring 433 to cooperate with such low portion 432b which releases the spring pressure on the clutch release arm 367 to free the latter for rocking to engage the type selecting clutch.

Upon transmission of such 0, X, R impulses through circuits to be described, the second energization of the magnet 361 again attracts its armature 415 and shifts link 416. The latter, thereupon rocks the clutch release arm 424 to unlatch the clutch release arm 388 of the printing clutch. At this time a low portion 420c (see Figs. 9a and 16b) of cam 420 cooperates with the cam follower extension 421 so as not to restrain the rocking of clutch release arm 424. When the clutch release arm 388 is unlatched a depending extension 427 moves in a clearance portion 426 of said arm 424. Cam disk 383 will now rotate clockwise and the cam extension 383 will strike the follower extension 384 at the time the selected type is at the printing line to effect the printing impression.

It is undesirable to have the clutch release arm 388 released whenever link 416 is rocked the first time to rock arm 424 and to this end a high portion 437a of cam 437 cooperates with arm 388 to block it against movement to release the printing clutch during transmission of impulses 1-9. When impulses 0, X and R are transmitted the low portion 437b of cam 437 (see Fig. 16b) will cooperate with clutch release arm 388 to permit its rocking to engage the printing clutch. After the transmission of the 0, X, R impulses the cam rise 437c of cam 437 will function to positively retract the clutch release arm 388 to normal position to cause disengagement of the clutch release pawl 387 after a complete revolution of the printing clutch. At the termination of the operating cycle, a cam rise 420d of cam 420 functions to rock the clutch release arm 424 counterclockwise to again position it beneath the extension 427 of the clutch release arm 388, which previously has been elevated to the position shown in Fig. 9a. The cam rise 420d also shifts link 416 to restore armature 415 to normal if it should stick to the core of magnet 361.

While the operation of the machine has been described in connection with the selection of the group of type under control of the 9 impulse the same principle of operation for effecting the above results is involved for other impulses as is evident from the following table:

Impulses	Members 410 Latched	Mechanical Impulse at—	Cams 400 at Medium Cam Portion
9.....	410A, 410C	Degrees 138	400B, 400D
8.....	410A	153	400B, 400C, 400D
7.....	410B, 410C, 400D	168	400A
6.....	410B, 410C	183	400A, 400D
5.....	410B, 410D	198	400A, 400C
4.....	410C, 410D	213	400B, 400A
3.....	410B	228	400A, 400C, 400D
2.....	410C	243	400A, 400B, 400D
1.....	410D	258	400A, 400B, 400C

It will be recognized from this table that the concurrent position of cams 400 at a "medium" height cam portion for those cams which have not previously latched members 410 will determine the time the mechanical impulse is transmitted.

The machine includes a driving means driven by the shaft 27 (Fig. 11) for rotating the cams 400A, 400B, 400C and 400D, 420, 425, 432, and 437 in synchronous relationship and such cams are driven one complete revolution for each operating cycle.

The driving means for driving cams 400A, 400B, 400C and 400D will now be described. Secured to shaft 27 is a gear 440 which, through a gear 441, drives a gear 442 secured to the drive shaft 443 for the cam 400D and cam 432. Shaft 27 is extended, as shown in Fig. 13, to directly drive the cam 400C. Referring to Fig. 11, gear 440, through a gear 444, drives a gear 445 secured to the drive shaft 446 for cam 400B. Gear 445 through an idler gear 447 drives a gear 448 secured to the drive shaft 449 for the cam 400A. By such driving means the cams 400A, 400B, 400C, 400D and 432 are driven synchronously.

Referring to Fig. 11 gear 444 has rotatable therewith a gear 450 which, through an idler gear 451, drives a gear 452 attached to the shaft 453 to which the cam 425 is secured.

Gear 450 also meshes with a gear 454 secured to a shaft 455 to which shaft the cam 420 is secured.

Also referring to Fig. 11 to drive shaft 388 driven by gear 381 there is secured a gear 456 which meshes with a larger gear 457 secured to a shaft 458 to which shaft the cam 437 is secured.

Thus, through the intergearing last described, the operating cams 420, 425 and 437 are driven synchronously with the operating cams 400A, 400B, 400C and 400D.

CF and CR cam contacts

As will be specifically referred to in the description of the electrical circuits, the machine is provided with CR cam contacts which are well known in construction and operation because they are continually opening and closing during each cycle of operation of the machine, and CF cam contacts which, in the present machine, open and close during card reading operations of the machine, instead of only card feeding operations, as in other record controlled machines.

The cams which operate the CR contacts may be driven by any suitable continually rotated shaft and herein may comprise the shaft 27 which, it will be recalled, is rotated one revolution for each operation of the machine.

The CF cam contacts are operated during each card reading operation of the machine by the arrangement shown in Fig. 2. Gear 28 (Fig. 2) secured to the shaft 27 which is rotated one revolution for each machine cycle drives a gear

282 to which is attached the clutch disk 283 of a one-revolution clutch to drive a shaft 284 one revolution for each clutch engagement. The one-revolution clutch is not described in detail since it is well known so that for each card read cycle the energization of CF cam clutch magnet 280 causes one revolution of the drive shaft 284. The shaft 284 carries the cams which close and open the related CF cam contacts.

Starting circuits

The initiation of card feed, the sequential card feeding operations and multiple line printing operations will, it is believed, be best understood by describing the operation of the machine in connection with the circuit diagram (Figs. 17a, etc.).

A prerequisite to initiation of card feed is that hopper contacts 270 (Fig. 17a) are closed and referring to Fig. 3 this is effected by the depression of a button 271 by cards in the supply magazine 25. When all the cards have been fed out of the magazine the contacts will open and the machine will automatically stop.

Current is supplied by lines 272 and 273. With hopper contacts 270 closed, an obvious circuit to energize R1 relay is closed and a stick circuit for said relay is provided by R1a relay contacts and cam contacts CR9.

Initiation of card feed is effected by depression of the Start Key which closes contacts 274 to close a circuit from the line 272, start key contacts 274, P or pickup coil of the start relay R9, to line 273. R9 is the start key relay. It should be noted that in the circuit diagram all relays and magnets are connected to line 273 to complete the energizing circuit. R9 relay closes its stick contacts R9a and a stick circuit is provided back to line 272 through cam contacts CR3 to hold the H or hold coil of the R9 relay energized over and through part of the second machine cycle. Obviously, when CR6 contacts open during the second machine cycle and if the Start Key is not retained depressed, R9 relay will de-energize and for this reason the start key is maintained depressed or redepressed until a third card issues from the magazine.

At 200° of a cycle while R9 relay coil is energized cam contacts CR86 close to complete a circuit from line 272, stop key contacts 277, CR86 cam contacts, R9b relay contacts, R10P relay coil, to line 273. The hold circuit for R10P relay coil is through R10a relay contacts and cam contacts CR7 which holds R10 energized until 235° of the next cycle. R10 is the start relay.

R10 relay closes R10b relay contacts, completing a circuit at 245° from line side 272, cam contacts CR5, R10b relay contacts, R11P relay coil, line side 273. A hold circuit is maintained by cam contacts CR4, through R11a relay contacts, CR4 holds R11 relay energized until 210° of the following cycle. When R11 relay closes its R11b contacts it completes a circuit from line side 272, R11b relay contacts, now closed, R30-1 contacts, now closed, CR97 cam contacts, picker clutch magnet 64, to line side 273, also energizing the pickup coil of the R12 relay in shunt with magnet 64.

R12a relay contacts complete the holding circuit for R12H relay coil through such contacts, and both CF2 cam contacts and R11b relay contacts back to line 272. The CF2 cam contacts take the arc at the breaking of the hold circuit instead of R11b relay contacts.

Energization of picker clutch magnet 64 at 250° when CR97 closes causes the engagement of the picker clutch at about 285° of the first ma-

chine cycle, and the lowermost card is then advanced from the supply magazine 25 to the constantly rotating feed rolls 50, 51, and the card is fed by the latter to the Presensing Station P (Fig. 4) and when this condition is obtained a card lever 275 (Fig. 3) is rocked to close the Presensing Station card lever contacts 276 at 140° of the second machine cycle, or the first card feed cycle, but are kept closed due to the presence of a card in the P station.

At 285° of the first machine cycle cam contacts CR88 close, completing a circuit from line side 272, R11b relay contacts, R4b relay contacts, CR88 cam contacts, CF clutch magnet 280, to line side 273. Energization of this CF clutch magnet will cause the engagement of the conventional one-revolution clutch to initiate rotation of shaft 284 at 310° which operates the CF contacts, as previously described. The above energizing circuit for the clutch magnet 280 is for the first machine cycle. In subsequent card feed cycles, as will be explained, and upon the presence of cards at station P the R3 relay will be energized to close the R3d relay contacts to impulse the clutch magnet 280. After the card lever contacts 276 are closed at 140° of the second machine cycle (or first card feed cycle) CR8 cam contacts close to complete an obvious circuit to R3P relay coil. R3a relay contacts then close to complete a holding circuit back to line 272 through the CF5 cam contacts. CF5 cam contacts extend the energization of the R3 relay over and through the next or second card feed cycle. When R3d relay contacts close during this second machine cycle and CF2 close during this and succeeding machine cycles, a circuit is completed to energize the CF clutch magnet 280.

The start key will be held down or depressed 40 the second time to reenergize R9 relay and the operation will be repeated to advance the card from the Presensing Station P to the first Control Station and to feed the second or following card from the supply magazine into the feed rolls 50, 51 and thus to the Presensing Station.

Energization of the R3 relay closes R3c contacts which, it will be recalled, are closed only when a card is at the Presensing Station so as to complete at 165° a circuit during the second machine cycle or first card feed cycle from the line 272 through CR3 cam contacts, R3c relay contacts, R12b relay contacts now closed, R30-2 relay contacts now closed, to the gripper clutch magnet 153. This clutch magnet, it will be recalled, causes the operation of the mechanism which closes the gripping devices to feed particularly the first card from the Presensing Station P to the first reading Control Station and other cards from station to station or to the stack or drum in the manner previously described.

Closure of cam contacts CF22 at 240° of the second machine cycle or first card feed cycle causes completion of a circuit from line 272 through cam contacts CF5 now closed, R3a relay contacts now closed, CF22 cam contacts to the pickup coil of the R4 relay. The latter will close the R4a relay contacts to complete a stick circuit for the H or holding coil of the R4 relay extending back through the R4a relay contacts, 65 R4c hopper relay contacts, or CF4 cam contacts during the cycle in which the last card passes the first reading Control Station, to line 272. R4 relay will thereupon open the R4b relay contacts so that the impulse emitter by CR83 cam contacts to the CF cam clutch magnet 280 will

be subsequently directed through the R_{3d} relay contacts for card feed cycles after the first. During the third machine cycle or the second card feed cycle cam contacts CF₂₃, which are timed to close slightly earlier than CF₂₂, will close and complete a circuit from the line 272 through CF₄ cam contacts, R_{4a} relay contacts now closed, CF₂₃ cam contacts to the pickup coil of the R₅ relay. The latter closes the R_{5a} stick contacts providing a stick circuit for the holding coil of the R₅ relay extending back through CF₃ cam contacts, or R_{5a} relay contacts and R_{1f} relay contacts back to line 272. CF₃ cam contacts control the deenergization of R₅ relay during the cycle in which the last card passes the Adding-Printing Control Station. R₅ relay closes R_{5b} contacts which in conjunction with R_{3b} relay contacts and R_{1b} relay contacts now closed provide an alternate holding circuit for the R₁₀ relay to keep R₁₀ energized when cam contacts CR₇ for the holding circuit of the R₁₀ relay open. It will thus be noted that R₄ relay is energized as the card is about to enter the first reading Control Station and that R₅ relay will later energize when the card is about to enter the Adding-Printing Control Station. Relays R₄ and R₅ also control relay contacts which supply current to the readout commutators shown as will be described in detail.

Under normal card feed conditions and so long as cards continue to feed through the Presensing Station P, the card picker control clutch magnet 64, CF cam control clutch magnet 233 and gripper control clutch magnet 153 will all be reenergized each cycle under normal conditions so long as cards continue to feed through the machine.

However, failure to feed a card from the supply magazine to the Presensing Station to close the contacts 276 will stop card feeding operations. Whenever the presensing card lever contacts 276 are opened, due to the failure of a card feed from the magazine, the stick circuit to the hold coil of the R₃ relay will be opened when test cam contacts CF₅ open at about 159° of the card feed cycle in which there is a card feed failure. Deenergization of R₃ relay enables the R_{3c} contacts to open, and assuming that there are cards in the hopper which would cause the R_{1e} contacts which are in multiple therewith to be opened, the impulse circuit to the gripper clutch control magnet 153 will be opened and it will not receive the impulse transmitted by the CR₃ cam contacts. The result of this is that the gripper clutch controlled by the magnet 153 will not be engaged and the card grippers will not be closed and cards present at the first reading Control Station and the Adding-Printing Control Station will remain in such position and will not be advanced. Also deenergization of the R₃ relay will cause the R_{3b} relay contacts to open, and assuming that the R_{1b} contacts are closed due to the presence of cards in the magazine, the holding circuit of the R₁₀ relay is deenergized upon opening of the CR₇ contacts at about 235° of the cycle in which there is a card feed failure. R₁₀ relay becoming deenergized opens its R_{10b} contacts, preventing the energization of the auto start relay R₁₁ when cam contacts CR₅ close. R_{11b} relay contacts 70 thereupon open with the result that the impulse circuit to the R₁₂ relay and the picker clutch control magnet 64 is opened and furthermore opening of the R_{3d} relay contacts prevents the transmission of an impulse to the card feed

cam clutch magnet 230. Since the clutch control magnets 153, 230, 64 for the three clutches will not be energized, all of the card feed operations will be terminated. Summarizing, during each cycle of operation, test circuits function to determine whether a card has been properly fed by the picker blade and the feed rolls to the intermediate Presensing Station.

Card analyzing or reading circuits

The circuits whereby the perforated cards may be analyzed at the first reading station and the second reading station are shown in Fig. 17b wherein it will be seen that for column 1 and column 80 the arrangement of the sensing or readout commutators is shown diagrammatically. Of course, while not shown this arrangement is duplicated for the 80 columns in each of the reading stations. The sensing or analyzing circuit for the first reading station is from the line side 272, the well known circuit breaker contacts CB, CF₂₈ cam contacts, to R_{4c} relay contacts which are closed during the perforation analyzing time. From the R_{4c} contacts there is a wire connection 500 to a half ring 501 which is common to all sensing commutators to connect one side of the line to each brush 165. It will be recalled that the brush 165 of the commutator makes successive contact with the contact points 164 so that the circuit will be closed through the corresponding brush 162 which passes through the card perforation. Each plate 161, which carries the series of analyzing brushes 162, has a wire connection to a respective plug socket 502. For the first reading station there is a series of eighty plug sockets 502 from which plug connections are made for control purposes.

The sensing or analyzing circuit for the second reading station extends from line 272, CB circuit breaker contacts, the CF₂₈ cam contacts, thence through the R_{5c} relay contacts to a wire 503 which is connected to a half ring for the brushes 165 of the sensing commutators for the second reading station. There is, likewise, a series of eighty plug sockets 504 for the second reading station from which plug connections are made to the desired printing orders to effect printing of information corresponding to the perforated data.

The CB circuit breaker contacts are timed to close and open at such times as will prevent the arcing at the break and make between the brush 165 and the contact points 164 so as to prevent damage at this point of contact. The construction and operation of such circuit breaker contacts, such as are employed herein, are well known.

Print magnet energizing circuits for normal single line printing operations

The energizing circuits for the printing control magnets 361 are shown in Figs. 17b and 17c. The machine is intended to have a capacity of 120 printing columns requiring a corresponding number of printing control magnets 361, although only a few are shown in the drawings.

As will be described in detail later on, the machine is capable of being conditioned for multiple card reading and multiple line reading and printing under control of a single master card which is passed through the card feeding and reading mechanism. However, it is at times desirable to print in the normal fashion, that is, to merely print a single line under control of one or more perforated fields in a detail card.

To accomplish this the desired plug sockets 504 of the second reading station have plug connections 506 made therefrom to plug sockets 505 (Fig. 17c) of the columns in which the printing is to be effected. The multiple plug wire connections 506 and others are shown, for simplicity, in part as a single cable. Therefore, according to the perforations in the card of the columns analyzed, impulses according to the code are directed to each of the plug sockets 505, the energizing circuit then extending, by way of example, for the column 1 printing order, through R16-1 transfer contacts now in normal position, thence through R15-1 transfer contacts now in normal position, to the print control magnet 361, to the line side 273. Hence the print control magnet 361 will receive impulses singly or in combination, according to the code in Fig. 15, depending upon whether numeral or alphabetical information is represented on the detail card analyzed at the second reading station.

When the data analyzed at the second reading station is numerical data the N impulse to energize the print control magnet 361 a second time to print the selected digit is transmitted by an energizing circuit from the line 272, through CR104 cam contacts which close between 183-198°, thence through all the transfer contacts of the R15 relay which are transferred at the time that CR104 cam contacts transmit an impulse. The R15 relay coil is energized between 180-295° by an obvious circuit which extends from line 272, through cam contacts CR20, R15 relay coil to line side 273.

General explanation of the multiple line reading and multiple line printing operations

A general explanation will now be given so as to understand the operation of the machine by means of which a specially designated record card, such as the master record 508 shown in Fig. 18 may, by reconditioning the machine, be repeatedly analyzed at the second reading station, and the record fields A, B and C control, in successive cycles of machine operation, a single bank of print control magnets 361, or a plurality of such banks if so desired, to print the three lines of the address on the form 509 by the alpha-numerical printing mechanism of the present machine.

As will be subsequently described in detail, circuits are rendered effective under control of the specially designated master card 508 to re-condition the machine for this form of recording as well as to control and determine the number of lines which are to be printed. In most cases three lines of printing or a complete address would be desired from one master card. However, there are other requirements where a master card is passed through merely for printing from one field only on one line, or two lines from two fields although other fields of line printing control data may be designated on the master card. In each case, however, the number of lines of printing is selected by the master card and requires the minimum number of cycles of operation of the machine so as to eliminate loss in time of machine operations.

The alpha-numerical printing mechanism is, as previously stated, controlled by the second reading station. In the assumed example the master card 508 (Fig. 18) is perforated at fields A, B and C to represent (A) the name; (B) the street address; and (C) the town and state. Accordingly, there are corresponding multiple plug wire connections 510, 511 and 512 (Fig. 17b) from

the plug sockets 504 of the second reading station corresponding to the card columns comprising fields A, B and C. These multiple plug connections terminate at plug sockets 513, 514 and 515 (see Fig. 17c) which are designated as Line 1, Line 2 and Line 3. These plug sockets are associated with progressive selectors which are in the form of three relays R17, R18 and R19 which are energized in succession to successively pick up the fields of the cards which are to control printing and in the sequence they are to control the printing mechanism. The progressive selector relay R17 for Line 1 has each of its plug sockets 513 connected to the relay contacts 1, 2, etc. so that upon the energization of the R17 relay, for example, the circuit connections are extended from plug sockets 513, through the series of R17 relay contacts, and wires 517 to a series of plug sockets 518 designated "Common." Thus, when R17 selector relay is energized the plug connections 510 which terminate at plug sockets 513 will be extended to the corresponding plug sockets 518. In the same manner when the R18 relay is energized the plug connections 511 terminating at the plug sockets 514 will be extended to Common plug sockets 518, and in the same manner plug connections 512 connected to plug sockets 515 are extended to the Common plug sockets 518 by the energization of the R19 relay.

From the series of plug sockets 518 there are multiple plug wire connections 520 to a series of plug sockets 521 designated as Transfer Print.

As will be later described in detail the R16 relay is energized to transfer all of its relay contacts so as to extend the circuit from each plug socket 521 through the respective transferred contact of the R16 relay, thence through the respective normal contacts of the R15 relay, to the corresponding print magnet 361. The plug connections 520 are shown plugged into a single series of plug sockets 521 of the same columns used for printing detail information and in such an arrangement the same printing orders are utilized to print the information on the detail cards, such as a policy number, the name, street and house number, town and state beneath each other, as shown on the printed record 509 in Fig. 19.

Of course, by varying the plug connections 510, 511 and 512 where they terminate at the Line 1, Line 2 and Line 3, plug sockets 513, 514 and 515, the lines of the address may be printed in any sequence. Also by varying the plug connections 520 from the plug sockets 518 to the plug sockets 521, the same or different printing columns may be utilized for printing at desired places on the record 509. Any plug connection 510, 511, 512 may be omitted to prevent printing of any line of the address. The wide flexibility resulting from the many possible plug connections enables a variety of reports to be printed and it is emphasized that the plugging connections shown in Figs. 17b and 17c are only one of many possible combinations and they are shown only for illustrative purposes and to correspond with the example shown in Fig. 19.

Conditioning of the machine for changing from single line printing to multiple line printing

As shown diagrammatically in Fig. 18 a detail card 507 may pass through the machine so that its field or fields of data may control the desired printing bank to print on a single line the corresponding information which is shown on the printed record 509 as the Policy Number

144152, and on the same line other information which may be derived from the detail card. This printing is effected in the cycle of machine operation in which the detail card is analyzed at the second reading station and at this time a following master card 508 is analyzed at the first reading station. If it bears a designation at the 12 index point position of a selected column, or the R index point position as it is otherwise known, it will condition the machine for multiple line printing under control of said master card when it arrives and is then repeatedly analyzed at the second reading station.

It is preferable to have this control exercised by each of the master cards and according to the present embodiment the control hole or special multiple line printing selecting designation consists of a perforation at the 12 or R index point position in a selected card column of the master card, as is shown in Fig. 18. To accordingly condition the machine for multiple line reading it is preferable to do this by a presenting at the first reading station so that when the master card arrives at the second reading station the machine is conditioned to effect multiple line reading and printing by successive cycles of machine operation. Referring to Fig. 17b it will be seen that a plug socket 502 of the first reading station corresponding to the column in which the MLR start designation is perforated at the R index point position has a plug connection 525 to a plug socket 526 (see Fig. 17d). Therefore, when the R index point position is sensed and a hole is found in the master card an impulse circuit is extended from the sensing commutator for the control column, by plug connection 525 to the plug socket 526 (Fig. 17d), thence through the normally closed contacts of R30-3 relay contacts, through the CF26 cam contacts, the pickup coil of the R20MLR start relay and a wire 527 to the line side 273. The CF26 cam contacts are timed to close between 172-180° at which time the R index point position is analyzed. When the R20 relay coil is energized it closes the "a" or hold contacts, thereby holding the R20 relay energized through such relay contacts and cam contacts CF14 back to line 272. The CF14 cam contacts hold the R20 relay energized until 340° of the cycle in which the master card is analyzed at the first reading station. R20 relay closes the R20-1 relay contacts, thereby extending a circuit from the line side 272 through CF13 cam contacts which close at 312° before the R20 relay coil is deenergized, thence through R20-1 relay contacts, the pickup coil of R21 relay coil, wire 527 to the line side 273. By a branch wire connection 528a a circuit is extended from the R20-1 relay contacts, through wire 528, the pickup coil of the R30 relay to the line side 273. A hold circuit for the R30 interlock relay is through the "a" relay contacts, R29-2 relay contacts, wire 529, back to line 272. This hold circuit is held by R29-2 contacts until the R29 relay coil is energized which takes place during the cycle in which the last multiple line reading and printing operation is performed under control of the master card. The purpose of the R30 relay, which is an interlock relay, will be presently described.

A hold circuit for the MLR Line 1 relay R21 is effected through the "a" contacts and CF11 cam contacts back to line 272. The CF11 cam contacts hold the R21 relay coil energized until 285° of the first multiple line reading cycle.

It will be recalled that the Transfer Print R16

relay coil shown in Fig. 17c is energized so as to complete circuits from the plug sockets 524 which receive the plug connections 520, to the print control magnets 361 during each multiple line printing operation, whether they comprise 1, 2 or 3 lines. Energization of the R30 relay coil closes the R30-4 relay contacts (Fig. 17d) so as to complete a circuit from the line side 272, through CF11 cam contacts, wire 522, wire 530, R30-4 relay contacts, R16 relay coil, wire 531 to the line side 273. Because the R30 interlock relay remains continuously energized during successive multiple line reading and printing operations the R16 relay coil is energized during the period that the CF11 cam contacts are closed, which is from 320° of a preceding cycle to 285° of each cycle in which a multiple reading and printing operation takes place. It will now be understood that the R16 relay coil is energized during the first multiple line printing and reading cycle when Line 1 is printed by the printing mechanism. It remains to be shown how the Line 1 progressive selector relay coil R17 (see Fig. 17c) is energized so as to complete circuit connections from the plug sockets 504 corresponding to the columns in which the name is represented, or Field A, with the print control magnets 361.

Energization of the R21 relay coil closes the R21-1 relay contacts (Fig. 17d), thereby completing a circuit from line side 272, through CF11 cam contacts, wires 528, 530, R21-1 relay contacts, R17 relay coil, wire 531 to line side 273. Thus, all of the contacts controlled by the R17 relay, shown in Fig. 17c, are closed, thereby extending the circuits from the plug sockets 513 to which the plug connections 510 are made to the plug sockets 518, from which plug connections 520 are made to the Transfer Print plug sockets 521. The R17 relay, therefore, remains energized during the same period of time that R16 and R21 relay coils are energized since all of them are maintained energized during the period CF11 cam contacts are closed.

As will be evident later on, there is no suppression of card feed in the cycle in which the master card is analyzed at the first reading station so that the master card is transported by means of the grippers in the card feeding unit, and fed between 195° and 315° to the second reading station for analysis by the sensing commutators at the second reading station.

It is also pointed out that during the first multiple line printing cycle during which the master card is analyzed at the second reading station the card picker and gripper feed mechanism is prevented from operating in the normal manner so as to retain the following card (master or detail) at the first reading station and the master card at the second reading station. When the master card has been fed to the second reading station it is aligned both vertically and horizontally to proper analyzing position and held there until the completion of the last multiple line reading operation. This is possible because circuits are effective during the first multiple line reading and printing cycle to prevent the card picker clutch and the card gripper clutch from engaging until completion of the last multiple line reading and printing operations. It will be recalled that the R30 relay coil is energized during the first and all the multiple line printing and reading operations and accordingly the R30-1 and R30-2 relay contacts (see Fig. 17a) are both open at impulsive time for

clutch magnets 64 and 153, thereby preventing the normal energizing circuit for the gripper clutch magnet 153 and the picker clutch magnet 64 from being closed. Therefore, no further cards will be fed from the magazine and the master card will remain at the second reading station until the completion of the multiple line reading and printing operations.

However, for the cycle in which the master card is analyzed at the first reading station the clutch magnet 64 receives its impulse at 250° and magnet 153 receives its energizing impulse 165° for engaging the respective clutches long before (at 312°) the R30 relay coil is energized so during this cycle of machine operation the following card is fed from the magazine to the Presensing Station P, and other cards from station to station, or the stacker drum in the manner previously described.

However, for each cycle of operation the CF cam clutch magnet 280 becomes energized in the normal manner by the impulsive circuit previously described, which is necessary because in the present machine the CF cams must operate to control cam contacts which are involved in the circuits for multiple line reading and printing. This is different from other forms of record controlled accounting machines wherein the CF cams operate only during the machine cycles in which a card is being fed and during nonfeeding cycles such cam contacts remain at normal position.

Understanding now that the first line of the address or the name is printed under control of field A, there will now be described the circuits which operate so that the second line, or the street address, is printed under control of field B of the same master card. This is accomplished by deenergizing the R17 progressive selector relay at the termination of the first multiple line reading cycle, which occurs when CF11 cam contacts open at 285° of the cycle. At the 265° of the first multiple line reading cycle cam contacts CR51 close to complete a circuit from the line 272, through CR51 cam contacts, R30-5 contacts which are now closed, through R20-3 relay contacts which are now closed, through R21-2 relay contacts which are now closed, the pickup coil of R22 relay, wire 527 to line 273. The hold coil for the R22 relay coil is through the "a" relay contacts and cam contacts CF14, precisely the same timing as explained for the R20 relay coil, so that R22H is held energized until 340° of the first multiple line reading cycle.

R22 relay coil closes the R22-2 relay contacts so that at 312° of the first multiple line reading cycle a circuit is completed from line 272, through cam contacts CF13, wire 532, through R22-2 relay contacts, the pickup coil of R23, wire 527 to line side 273. The R23 hold coil is held through the "a" contacts and CF11 cam contacts until 285° of the second multiple line reading cycle. R23-1 relay contacts close to pick up, by an obvious circuit, the R18 progressive selector relay and in the same manner, as has been described, for the R17 and R21 relays. The R23 and R18 relays are held energized until 285° of the second multiple line reading cycle. With the R18 progressive selector relay now energized, circuit connections will be closed between the plug sockets 514 and 518 (Fig. 17c), thereby transmitting impulses according to the perforations in field B to the printing control magnets 361, causing the printing of the second line of the address.

The printing mechanism of the present ma-

chine includes the usual platen 390 (Fig. 9a) carrying the printed form or sheet 509 and furthermore includes the customary line spacing device for the rotating of the platen so as to space the printed sheet one line as an incident to each line printing operation to separate the successive lines of printing. Since the platen line spacing devices are well known their further description is deemed to be unnecessary. Accordingly, the second line of the address will be spaced from the first line as shown on the form 509 in Fig. 19.

Since, during the second multiple line reading cycle the R30 relay coil is still energized, impulses cannot yet be transmitted to the gripper clutch magnet 153 and the picker clutch magnet 64. Hence, the master card 508 will still remain at the second reading station and a third multiple line reading and printing cycle takes place exactly in the same manner as has been described for printing lines 1 and 2.

At the end of the second multiple reading cycle, R24 coil becomes energized and it, in turn, picks up the R25 relay coil which is held energized during the third multiple line reading and printing cycle. The R25 relay coil closes the R25-1 contacts (Fig. 17d), thereby energizing the R19 progressive selector relay. This progressive selector relay R19 coordinates field C of the master card with the print magnets 361 so that the printing mechanism will print the third line of the address. This will complete printing of the address from the master card. As will be subsequently explained in detail, special designations are placed on the master card which function to determine the number of lines which are to be printed, and assuming that three lines are to be printed from the same card as has been explained the circuits are now conditioned differently at the termination of third multiple line printing.

As is shown in Fig. 18 the perforation which is to select and determine the number of lines of printing is placed in the same column that the R hole is located and when the master card is analyzed at the second reading station the sensing commutator associated with such column will transmit a differentially timed impulse according to whether there is a supplemental hole at the 3, 2 or 1 index point position, which selects the corresponding number of lines of printing. In the present example, assuming three-line printing for a complete address, there is a perforation at the 3 index point position so that in each multiple line reading and printing cycle this column is analyzed but it is only during the third multiple line reading cycle that a circuit is effective to terminate multiple line reading and printing operations. From the plug socket 504 of the second reading station associated with the column having this line number control, a plug connection 535 is made (see Fig. 17b) which terminates at the STOP plug socket 536 (Fig. 17d). The circuit from the plug socket 536 is completed only during the third multiple line reading cycle, through cam contacts CR98 which are timed to close when the "3" index point position is analyzed, thence through the R25-4 relay contacts which close during the third multiple line reading cycle, the pickup coil of the R29 relay, wire 527 to the line side 273. A hold circuit for the R29 relay is completed through the "a" hold contacts and CF11 cam contacts back to line 272. R29 relay opens the R29-2 relay contacts so as to deenergize the R30 interlock relay but the final deenergization of the

R30 relay is controlled by the CF12 cam contact to deenergize R30 relay at 150° of the third multiple line reading and printing cycle.

Referring to Fig. 17a the closure of the R30-2 relay contacts enables the gripper clutch magnet 153 to be energized at the normal time or 165° (see Fig. 16a). The grippers now feed the master card from the second reading station to the stacker drum, the card (master or detail) at the first reading station to the second reading station, and the card (master or detail) at the presensing station P to the first reading station.

Due to the fact that R30-4 relay contacts (Fig. 17a) are now closed, an impulse will be directed to the picker clutch magnet 64 which will cause feeding of a card from the magazine to the presensing station P. The type of ensuing operations will then be determined by the type of card which is analyzed. In the event that a second master card follows, the control for multiple line printing will be reinitiated and multiple line reading will take place under control of the next master card according to the designations thereon. If the card following the master card happens to be a detail card there will be a single line of printing under control of such card.

When the R30-4 relay contacts open early in the cycle the R16 relay (Fig. 17d) would deenergize at 90° for three line printing but due to the closure of the R29-2 relay contacts the R16 relay is held energized under control of CF11 cam contacts until 285° of the third multiple line printing cycle. This is necessary because of the fact that beyond 150° of this cycle alphabetical information may be read from the card so that the coded alphabetical impulses may be properly transmitted to the printing control magnets 361.

Selective control for determining the number of lines to be printed under control of a card

It is preferable to have the master card itself select the number of lines which are to be printed since, in one instance, it may be desirable to print only the name, and in other instances both the name and street address. Accordingly, a perforation at the 1 index point position will terminate printing and card reading when a single line has been printed and a perforation at the 2 index point position will enable two lines of printing. The control for the selective operations is shown in Fig. 17d wherein it will be seen that there are two cam contacts CR96 and CR97 which close when a 1 index point position is analyzed and when the 2 index point position is analyzed. When printing a single line the R21 relay coil is energized to close R21-4 relay contacts. Upon the presence of a perforation at the 1 index point position the circuit is extended through CR96 cam contacts, R21-4 relay contacts to the MLR Release relay R29. In the same manner, a perforation at the 2 index point position enables the CR97 cam contacts to transmit an impulse through the R23-4 relay contacts to the R29 MLR Release relay when two lines have been printed. The operations which follow the termination of one or two multiple line printings are the same as those which are carried out at the termination of printing three lines, as previously described.

Summarizing, the additional selective control enables a single setup made by the operator, which constitutes the plug connection 535, to differentially select the number of printing cycles and lines to be printed and to confine them to

1, 2 or 3, in accordance with the corresponding perforation on the same master card.

Repeating multiline printing

There are times when it is desirable to repeat printing of 1, 2 or 3 lines of the address upon the result sheet. By the use of the arrangement previously described and the use of additional electrical instrumentalities it is possible to rearrange and condition the machine so that three lines of the address will be printed in the manner previously described and thereafter repeat the multiline printing so as to duplicate this information. The arrangement is shown diagrammatically in Fig. 20 and additional electrical instrumentalities are shown mostly in Fig. 17e, whereas Fig. 21 shows a result sheet 540 wherein it will be seen that three lines of the address are printed in duplicate. In the printed sheet 540 shown in Fig. 21 this information is printed in duplicate because the billing and the shipping addresses are identical. If so desired, the use of a form with a stub will enable the address to be printed in duplicate on the form and stub so that the stub may be detached from the bill and used for the address on a package having the articles referred to on the bill, which are printed under control of the succeeding detail cards.

It is also desirable at times to call this duplicate printing for operation at selected times and to this end there is provided a selective repeat address control.

The card 508 shown in Fig. 20 is the Master card and corresponds to the Master card previously described. At a selected column it contains a hole at the 12 or "R" index point position which conditions the machine for multiline printing; a second hole at the 1, 2 or 3 index point position which determines the number of lines to be printed under control of the Master card, and a third hole at the 11 or "X" index point position which causes, by its presence the repeat printing of the selected number of lines. Its omission prevents this function and enables each Master card to be used only once for controlling printing of three lines, or one name and address.

To provide for the selective control of repeat multiline printing the plug connection 535 shown in Figs. 18 and 17b, c and d is omitted and instead there is interposed between the plug socket 504 corresponding to the column used for control and the plug socket 538, the "b" contacts of a relay R47 (see Fig. 20). When there is no hole at the 11 index point position the R47 relay is not energized so that the circuit extends from plug socket 504, plug wire 541, through the relay contacts R47b now closed, plug wire 542 to the plug socket 538. In the manner previously described three multiline printing operations under control of the card at the second reading station will be terminated.

The start of multiline printing operations is placed under control of the card 508 when it is analyzed at the first reading station, and to this end the Master card 508 has a special hole at the "R," or 12th index point position (see Master card in Fig. 20). When this selective control is used plug wire 525 (Figs. 17d and 18) is also omitted. When the card is at the first reading station a circuit is completed when the R hole is sensed from the plug socket 502 of the column used for control (see Fig. 17b), plug wire 543 (see Fig. 20), plug socket 544, to a digit selector D. S. (now see Fig. 17e). The timing of the digit selector D. S. is shown in Fig. 16c. When the

readout commutator 161—165 (Fig. 17b) senses an R hole the circuit is completed by the digit selector when its brush hits the "R" contact point, to thus extend the circuit to the "R" plug socket 545, and by plug wire 558 (Fig. 20) to plug socket 526. It will be remembered that plug wire 525 to plug socket 526 shown in Fig. 17d is now omitted. The rest of the circuit is shown in Fig. 17d as extending from plug socket 526, R30-3 relay contacts now normal, CF26 cam contacts which close at the "R" index-point position (see timing in Fig. 16c), the pickup coil of R20 or the MLR Start relay, wire 527, to line 273.

The machine will now operate in the manner previously described to print three lines of the address under "Bill To" of the bill shown in Fig. 21. With this arrangement the number of lines to be printed for the first multiline printing operation and the repeat multiline printing is also controlled by the master card 508, as for only one name and address printing operation. As was previously described the holes at index points 3, 2 and 1 select the desired number of lines. From plug sockets 548, 549, 550 (see Fig. 20) of the digit selector D. S. one plug connection is made to the respective plug socket 553, 552, 551, depending upon the number of lines to be printed. Since three lines are now assumed to be printed, a plug connection 555 (Figs. 17e and 20) is made. When the 3 hole is sensed at the first reading station in the early part of the cycle the circuit extends from the digit selector plug socket 550, plug wire 555, plug socket 551, pickup coil of R40 relay, wire 557 to line side 273. A stick circuit for R40 is provided by the "h" contacts, and cam contacts CR30 (see timing in Fig. 16c), back to line 272. When CR30 cam contacts close at 295° before CR30 open at 330°, a circuit is completed from line side 272, the R30-6 (MLR Interlock) relay contacts now closed, CR31 cam contacts, relay contacts R40-1, pickup coil of R41, wire 557 to line side 273. A stick circuit for R41H is through the R41h contacts and either the R30-7 relay contacts or CF10 cam contacts back to line side 272. Cam contacts CF10 are shunted by the R30-7 relay contacts. When CF10 contacts open at 287° of the first multiline printing cycle R41 relay is held energized for six multiline printing cycles by the R30-7 relay contacts, because as previously described, R30 relay is picked up at the same time as R20 relay and held in this operation for six cycles. In the sixth cycle the R30 relay drops out at 150° but CF10 cam contacts hold R41 energized until 287° of the last multiline printing cycle.

The master card 508 (Fig. 20) also has a hole at the X position to pick up an X selector relay R47. When the X hole is sensed at the first reading station, the circuit is completed by the brush of the digit selector D.S. (see Fig. 17e), to plug socket 546, plug wire 556, plug socket 554, pickup coil of R46 relay, wire 557, to line side 273. A hold circuit for R47 relay is through its "h" contacts, and cam contacts CR30. By the circuit from line side 272, relay contacts R30-6, cam contacts CR31, relay contacts R46-1, a pickup coil of R47 relay is energized, R47 being connected to line side 273. The stick circuit for R47H is through its "h" contacts, and cam contacts CF10, or relay contacts R30-7. R47 relay is therefore held for six cycles, since it has the same hold circuit as the R41 relay.

In the preceding description of the operation of the machine for only three multiline printing operations, a circuit was described for normally

terminating three-line printing and in this case was completed by a plug wire connection 536 between plug socket 504 to 536. The R47b relay contacts are shown in the diagrammatic view of Fig. 20 as being interposed in this circuit and since they have now been transferred, the stop circuit cannot be completed now and three additional line printings from the same master record will be initiated to repeat the name and address printing on the bill 540, under "Ship To." The detailed circuit is as follows:

Since the R30 relay is still energized in the third cycle the R30-2 relay contacts (Fig. 17a) will remain open, and the gripper magnet 153 will not be energized to feed the card out of the second reading station. Also R30-1 contacts are open to prevent picker clutch magnet 64 from being energized. By initiating circuits now to be described, the same master card 508 will again be re-sensed to cause multiline printing, in the same manner previously described.

At the end of the third reading cycle the MLR Start relay R20 (Fig. 17d) is again set up to initiate the repeat multiline printing. While the third line is being printed the R49 relay is energized until 285° by CF11 contacts, as has been previously described. At "R" time of the third reading cycle a circuit will be completed to again pick up R20 relay when CF26 cam contacts close at 168°. The circuit is from line side 272, cam contacts CR50 (see Fig. 17e) having the timing shown in Fig. 16c, plug socket 560, plug wire 561 (now see Fig. 20), R48b relay contacts now closed, plug wire 562, R47a relay contacts now closed, plug wire 563, plug socket 518 Common, a set of relay contacts of R19 which (now see Fig. 17c) are between plug wires 563 and 564 and are now closed, plug socket 515 for line 3, plug wire 564, R41a relay contacts now closed (see Fig. 20), plug wire 565, plug socket 566 (now see Fig. 17d), the R30-3 relay contacts now transferred (since it will be recalled that R30 relay is still energized), through CF26 cam contacts (since in this machine the CF contacts operate in each card reading operation), pickup coil of the R20 MLR Start relay, wire 521 to the line side 273. There is also another circuit from the plug socket 566 by a wire connection 567 to the pickup coil of the R26 Advance relay and wire 527 to line side 273. The hold circuit for R26H is through the "a" relay contacts and CF14 cam contacts back to line 272. R26 relay closes R26-2 relay contacts, thereby preparing a pickup circuit for R27 relay when CF13 contacts close at 312° before CF14 opens at 340°, this circuit being from the line side 272, through CF13 cam contacts, R26-2 relay contacts now closed, R27P relay coil, wire 527 to line side 273. The hold circuit for R27H is through R27a relay contacts and R29-2 relay contacts, wire 529, to line side 272. Hence, R27 relay is held energized until MLR Release Relay R29 is energized.

At the end of the third cycle when R27 is picked up at 312°, a circuit is completed from the line side 272, through CR2 cam contacts now closed (Fig. 17e), R27-2 relay contacts now closed, the MLR Repeat Couple plug socket 570, plug connection 571, plug socket 572, to R48P relay coil, wire 557, to the line side 273. The hold circuit for R48H is through the "h" contact and cam contacts CR33 back to line side 272. The Co-Selector relay R48 remains energized during the fourth cycle and to the end of the sixth printing cycle because the R27 relay is held energized and CR2 cam contacts overlap CR33 cam

contacts. R48 relay now being energized, it will open its "b" contacts (see Fig. 20), thereby preventing the completion of the previously described impulse circuit during the sixth printing cycle to the MLR Start relay R20 and the R25 relay. In other words, R48b relay contacts are interlock contacts to prevent a second repeat operation of the machine after the sixth cycle.

In the manner previously described, and since it is assumed that three multiline printing operations will be performed for the repeat name and address printing operation, the fourth, fifth and sixth printing cycles will ensue, thereby again printing the name and address on the bill in Fig. 21 under "Ship To." During the sixth cycle of operation circuits are now effective to terminate multiline printing operations.

The termination of multiline printing at the end of the sixth cycle is effected under control of the line selecting hole (3 in this instance). The readout commutator of the associated column reads out the "3" hole at 93° to complete, during the sixth printing cycle, a circuit from line side 272, through the readout commutator, plug socket 504 (see Fig. 17b), plug wire 575 to the R48a relay contacts (see Fig. 20) which now being closed extend the circuit by plug wire 576 to plug socket 536. From this plug socket 536 (see Fig. 17d), the circuit is completed by the CR98 contacts (which also close at 93°) and R25-4 relay contacts (which close in the sixth cycle) to P2 pickup coil of the MLR Release Relay R29, wire 527 to the line side 272.

R29 relay opens the R29-2 relay contacts to deenergize the R30 or MLR Interlock relay. The functions of the R29 and R30 relays have previously been described, it being noted that R30 relay will now open the R30-1 relay contacts (Fig. 17e) thereby deenergizing the R41 and R47 relays when CF10 contacts open. Deenergization of the R30 relay and closure of R30-2 contacts (Fig. 17a) enable the gripper clutch magnet 153 to be energized to feed the master card out of the second reading station to the stacker drum and a following card thereto. R30 relay will also enable, by closure of R30-1 relay contacts, the energization of the picker clutch magnet 64 which will cause feeding of a card from the magazine to the presensing station.

As an alternative type of control for terminating line printing operations before three-line printings are accomplished in the repeat operation, suitable plug connections may be made to limit the number of printed lines to two or one. For a one-limit control, the circuit is as follows: From line side 272, cam contacts CR50 (Fig. 17e), plug socket 569, plug wire 575, plug socket 513 associated with R17, Line 1 relay contacts (see Fig. 17c), through these contacts, plug socket 518, plug wire 576, plug socket 577 (Fig. 17d), P1 pickup coil of the R29 relay, wire 527 to line side 273. Thus, only one line, or only the name, will be printed on the bill 540 under "Ship To" (Fig. 21). In this alternative arrangement four printing cycles will take place, operations thereafter being terminated, as previously described. If two lines are desired the contacts of R17 are used in this circuit.

Line selecting means for repeat operations

It has been assumed in the present example that three lines of printing are to be effected for the first and repeat address printings, due to the plug connection 555 (see Fig. 20). However, if it is desired that only one line be printed for

both address printing operations a plug connection will be made from plug socket 548 to 553.

If two lines are desired a plug connection will be made from plug socket 548 to the plug socket 552. For printing one line both R44 and R45 relays are utilized, which relays and circuits are the same as R40 and R41 relays. For two-line printing R43 and R42 relays are utilized and they have similar circuits and will operate in the same manner. Also, R47 and R48 relays are picked up and operate in the same manner as has been described for repeat address printing.

It is also shown diagrammatically in Fig. 20 how the R43 and R45 relays are plug wire-connected like the R41 relay so as to cause multiline Repeat operations after the desired number of 1 or 2 lines have been printed in the first address printing operation. With such plug connections R43 and R45 relays will function exactly as has been described for the R41 relay.

While there have been shown and described and pointed out the fundamental novel features of the invention, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a machine for printing the same multiline information or address twice under control of a single address bearing record, sensing means for said record, means for printing under control of said sensing means said multiline address once, means automatically operable upon completion of printing of the address the first time to again initiate the operation of the preceding named address printing means to print the same address a second time under control of the same record, said initiating means attempting, upon completion of printing the address a second time, to again initiate the operation of the initiating means to print the same address a third time, and means controlling said last named initiating means and operable upon completion of printing the address a second time to prevent the initiating means from again being operable upon completion of printing the address a third time.

2. In a machine for effecting a single multiline address printing operation and automatically and selectively effecting a repetition of said multiline address printing operation under control of the same address data representing record, means for sensing said address data, printing means, means operable when initiated for causing said printing means under control of said sensing means to print a first multiline address, means automatically operable when rendered effective upon completion of printing the first address to reinitiate the operation of said preceding means to repeat the printing of the address under control of the same record, and selective means controlling said last named means for rendering said last named means effective to reinitiate a repeat multiline address printing or ineffective to reinitiate a repeat multiline address printing.

3. In a machine for printing data in a multiline manner derived from a data representing record once, or if desired a second time upon detection of a special designation, means for detecting said special designation, means for sensing the data represented by said record, means for feeding a record into and out of cooperation with said

sensing means, means normally operative upon completion of the first multiline printing operation to cause said feeding means to eject said record, means for printing under control of said sensing means data derived from the record in a multiline manner, and selective means comprising means under control of said detecting means effective upon detection of said special designation to suppress the operation of said normally operative means to prevent the feeding means for ejecting the record to thereby retain the latter in cooperation with said sensing means, and to cause the sensing means to again sense the record and to again effect the operation of the multiline printing means whereby said printing means prints the data derived from the same record in a multiline manner a second time.

4. In a machine for printing data in a multiline manner derived from a data representing record once, or if desired a second time, said record having designations to represent the number of lines to be printed, means for sensing the data represented by said record, means for sensing said designations, means for feeding a record into and out of cooperation with said sensing means, means normally operative upon completion of the first multiline printing operation to eject said record, means for printing under control of said sensing means data derived from the record in a multiline manner, means under control of the designation sensing means to control said printing means to cause the latter to print a selected number of lines, means to again effect the operation of the multiline printing means, and selective means comprising means to render said normally operative means inoperative to prevent the ejection of the record to retain the latter in cooperation with said sensing means, whereby said printing means prints the data derived from the same record in a multiline manner a second time, and a number of lines a second time as determined by said designation sensing means.

5. In a record controlled printing machine, a single sensing means for sensing and repeatedly sensing a plurality of data representing parts of the same record and having several sections for sensing said data representing parts, reading out means cooperating with said sensing means for reading out the data sensed by each section of said sensing means, printing means, means for operatively associating the printing means with the sections of said sensing means for said parts of the record in succession as said record is repeatedly sensed whereby said printing means under control of said reading out and sensing means prints the sensed data parts a first time line by line, and means to effect a second operation of said preceding means to cause said printing means to print the sensed data parts a second time, line by line.

6. In a cyclically operable record controlled multiline printing machine controlled by perforated records having data represented in a plurality of parts, a single sensing means for repeatedly sensing the plurality of parts of the record and having several sections for said data representing parts, printing means, progressively operated means for directly and operatively associating the sections of said sensing means for said parts of the record in succession with said printing means as said record is repeatedly sensed whereby said printing means may be operated to print said data parts a first time line by line, and means automatically operative upon completion

of said first line by line printing to cause said progressively operated means to again operatively associate the sections of said sensing means for said data parts of the record in succession with said printing means to thereby print said data a second time line by line.

7. In a cyclically operable record controlled machine capable of effecting printing from one record or multiline printing from another record once or twice, said other record having two special designations, one for conditioning the machine for multiline printing, and another to determine whether multiline printing should be effected once or twice, sensing means for said data representing designations, and other sensing means for said special designations, printing means controlled by said data sensing means to normally print data under control of said one record, devices for controlling said printing means to effect under control of said data sensing means line by line printing of the data on said other record, means controlled by said sensing means for said one designation to cause the operation of said devices when multiline printing should be effected, and means controlled by said other sensing means for said other designation to control said devices to effect one or two operations of said devices to print the data on said other record once or twice.

8. In a cyclically operable record controlled machine capable of effecting printing from one record or multiline printing from another record once or twice, said other record having three special designations, one for conditioning the machine for multiline printing, another to determine whether multiline printing should be effected once or twice, and still another to select the number of lines to be printed, sensing means for said data representing designations, and other sensing means for said special designations, printing means controlled by said data sensing means to normally print data under control of said one record, devices for controlling said printing means to effect under control of said data sensing means line by line printing of the data on said other record, means controlled by said sensing means for said one designation to cause the operation of said devices when multiline printing should be effected, means controlled by said other sensing means for said other designation to control said devices to effect one or two operations of said devices to print the data represented by said other record once or twice, and means controlled by the sensing means for said still other designation to control said devices to select the number of lines to be printed for each multiline data printing operation according to said still other designations on said other record.

9. In a machine for automatically effecting repeated multiline address printing operations under control of the same address data representing record having several data representing parts, means for sensing said address data representing record, means for effecting a repeated operation of said sensing means for repeatedly sensing the record during the first and second multiline address printing operations under control of the same record, printing means, means under control of said sensing means for causing the printing means to be successively set in accordance with the several data representing parts to print the address data line by line a first time, and means controlling said preceding means and automatically operable upon the completion of the printing of the first multiline address

printing to reinitiate the operation of said preceding means to cause, as said sensing means again senses the same record, the printing of the address data line by line a second time.

10. In a machine for automatically effecting repeated multiline address printing operations under control of the same address data representing record having several data representing parts and designations representing the number of lines to be printed, means for sensing said address data representing record, means for sensing said designations, means for effecting a repeated operation of said sensing means for repeatedly sensing the record during a first and second multiline address printing operation under control of the same record, printing means, devices under control of said sensing means for causing the printing means to be successively set in accordance with the several data representing parts to print the address data line by line a first time, means under control of said designation sensing means for controlling said devices for selecting and determining the number of data representing parts which are to be utilized to set said printing means, and means controlling said devices and automatically operable upon the completion of the printing of the first multiline address printing to reinitiate the operation of said devices to cause, as said sensing means again senses the same record, the printing of the address data line by line a second time under control of the same record and a number of lines determined by the number of lines designations.

11. In a machine for automatically effecting repeated multiline address printing operations under control of the same address data representing record having several data representing parts and a designation indicating the reinitiation of the address printing operation, means for sensing said address data representing record, means for sensing said designation, means for effecting a repeated operation of said sensing means for repeatedly sensing the record during a first and second multiline address printing operation under control of the same record, printing means, means under control of said sensing means for causing the printing means to be successively set in accordance with the several data representing parts to print the address data line by line a first time, and means under control of said designation sensing means for controlling said last named means and automatically operable upon the completion of the printing of the first multiline address printing and sensing of said designation to reinitiate the operation of said last named means to cause as said sensing means again senses the same record the printing of the address data line by line a second time under control of the same record.

12. In a machine for automatically effecting repeated printing operations under control of the same data representing record, means for sensing said data representing record, means for sensing a designation serving to reinitiate a printing operation, means for effecting a repeated operation of said sensing means for repeatedly sensing the record for a first and second printing operation under control of the same record, printing means, means directly under control of said sensing means for causing the printing means to be set in accordance with the data on the record to print the data a first time, and means under control of said designation sensing means upon sensing said designation and automatically operable upon the completion of the

printing of the first printing operation to reinitiate the operation of said preceding means to cause, as said sensing means again senses the same record, said printing means to print the same data derived directly from the same record a second time.

13. In a machine for automatically effecting repeated printing operations under control of the same data representing record having a designation serving to cause the reinitiation of the printing operation, means for sensing said data representing record, means for sensing said designation, means for effecting the repeated operation of said sensing means for repeatedly sensing the record for a first and second data printing operation under control of the same record, printing means, means under control of said data sensing means for causing the printing means to be set in accordance with the data on the record to print said data the first time, and selective means under control of said designation sensing means for controlling said last named means and automatically operable upon the completion of the printing of the first data printing and sensing of said designation, to reinitiate the operation of said last named means to cause as said sensing means again senses the same record the second setting of said printing means to effect the printing of the data derived from the same record a second time.

14. In a machine for printing data derived from the same data representing record twice upon detection of a special designation, means for detecting said special designation, means for sensing the data represented by said record, means for feeding a record into cooperation with the sensing means to sense the record at rest and out of cooperation with said sensing means to eject the record after a sensing operation, means normally operative upon completion of the first printing operation to cause said feeding means to eject said record, means for printing under control of said sensing means data derived from the record, and selective means comprising means under control of said detecting means and effective upon detection of said special designation to suppress the operation of said normally operative means to thereby prevent the feeding means from ejecting the record to thereby retain the latter at rest in cooperation with said sensing means for sensing the record a second time, and to cause the sensing means to again sense the record while at rest and to again effect the operation of the printing means, whereby said printing means prints the data derived from the same record a second time.
